UNITED STATES PATENT OFFICE.

EDWARD HETT, OF NEW YORK, N. Y.

LITHOGRAPHIC-PRINTING PRESS.

SPECIFICATION forming part of Letters Patent No. 637,568, dated November 21, 1899.

Application filed June 1, 1896. Serial No. 593,796. (No model.)

To all whom it may concern:

Be it known that I, EDWARD HETT, a citizen of the United States, residing at New York, (New Dorp,) in the county of Richmond, State 5 of New York, have invented certain new and useful Improvements in Lithographic-Printing Presses, of which the following is a specification.

The present invention has reference to 10 printing-presses, and especially to multicolor lithographic printing presses employing a central impression-drum and a series of surrounding cylindrical printing-surfaces and series of inking and dampening mechanisms, with ink 15 and water supply systems.

It has for its special object to secure and perfect the realization of multicolor lithographic printing and to supplement and to 20 carry out to a practical and successful conclusion the methods and inventions heretofore devised by me to that end.

It consists of the mechanisms and combinations herein set out that are novel and patentable.

25 In a pending application—to wit, Serial No. 695,281, filed by me November 2, 1898—I have set out at large and claimed the improvements in general method that I have devised in the art of printing, and as the present invention is subordinate thereto and addressed 30 to one of the branches thereof and assumes for its practical success some of the earlier stages thereof I will here, besides referring to said application, briefly set out in outline 35 the said improvements in method as introductory to a description of the present invention.

Heretofore in the art of producing by lithography pictures that have a large plurality of colors the effort and practice have been to produce the picture with as few impressions (in number) as possible, and hence with as few colors as possible, and to that end the practice of the lithographic artist has been to select 45 as his colors a relatively small number of such basic or primary colors as by their combinations in the printing will give a fair approximation to the colors of the picture to be reproduced, and then to painstakingly proceed 50 to so draw the series of color-stones for these primary or basic colors as to cause them to repeat or overlay their respective colors

upon one another in layer upon layer, thus attaining approximately the different distinct colors of the picture by blendings and repetitions achieved in the printing, and then to print separately the different primary or basic colors at intervals of time allowing thorough and complete drying between printings. The effort and practice have been to reduce the 55 number of primary or basic colors to a minimum, for each additional color employed has ordinarily meant another handling through the press of the entire edition printed, and to that end the effort and practice have been 60 to increase the repetitions and overlayings of colors to a maximum. In ordinary lithographic work it is consequently the practice to introduce the primary or basic colors to a greater or less extent—that is, in fuller or 65 lighter tints, controlled by the fullness or lightness of the drawing—in almost every part of the picture, almost all of the separate distinct colors of the picture being produced by a large plurality of repetitions or overlayings of the 70 different primary or basic colors employed. This principle or practice of attaining the separate distinct colors of a picture by compounding, as it were, different primary or basic colors in the printing requires that the 75 printing of the different primary or basic colors be done not in approximately instantaneous succession, but with drying intervals between, for it is a well-known fact that whereas the first color printed on paper will 80 dry practically instantaneously, and so with a second color printed over the first, and so, indeed, with four colors printed one over the other, still four marks the limit, approximately, of practically instantaneous drying, 85 and each subsequent color printed over the preceding four or more colors will dry only comparatively slowly, and so after each such 90 subsequent printing or repetition a substantial drying interval must be allowed between 95 printings. This drying interval is incidentally provided in the ordinary and usual method of lithographic printing, where one color is printed at a time, and the entire edition or a substantial part of it passes through the 100 press for one color before it passes through the press for a subsequent color. Heretofore also it has been the practice in the art of lithography, in preparing the printing-sur-

faces for the several separate colors, to so transfer the drawings for each separate color that the position of the transfer on one printing-surface has had no particular or definite relation to the position of the transfers on the other printing-surfaces constituting the series and to empirically regulate the position of each transfer in the printing-press itself before beginning the printing by adjusting the printing-surface or the press, or both, until its transfer registers with the already-printed impressions on the sheets as they are fed in and to painstakingly feed sheet after sheet of the edition accurately to that register and so that the new impression registers with the preceding impressions. Thus the whole burden of attaining accurate registry has been thrown on the printing-department. Heretofore also it has been the common practice in lithography, as stated above, to print the successive colors not in approximately instantaneous succession—as, for instance, in one and the same press at one and the same time—but one impression or color at a time, with substantial intervals of hours or, perhaps, of days between the printing of one color and the printing of the next color.

My improvements in the art reverse the present practice in almost all of its leading and important features. Instead of building up the separate distinct colors of a picture by starting with a minimum of different basic colors and compounding them in and by the printing through a maximum of repetitions or overlayings achieved in the drawings, I attain the separate distinct colors of the picture to be produced, or substantially all of them, by separately mixing each of said separate distinct colors apart from and prior to the printing and as accurately as desired, preparing a large plurality of separate color-printing surfaces, substantially as many as there are separate distinct colors in the picture to be produced—a maximum of colors and a maximum of color-printing surfaces—and preparing these color-printing surfaces for a minimum of repetitions or overlayings, in no case more than will in the printing dry (all of them) approximately instantaneously, (and preferably only such as are required artistically, as for drawing, depth, or finish,) and finally printing from all of said color-printing surfaces in any desired succession. Again, instead of so transferring the drawings for each separate color that the position of the transfer on one printing-surface has no actual or necessary relation to the position of the transfers on the other printing-surfaces constituting the series, but experimentally regulating the position of each transfer in the printing-press itself before beginning the printing by adjusting the printing-surface or the press, or both, and painstakingly feeding the sheets of paper into the press accurately sheet by sheet with reference to the particular adjustment of the printing-surface in the press, I so transfer the drawings from the

ries of color stones or surfaces that have been prepared by the artist to a series of printing-surfaces in accurate and related register throughout the series that the position of each transfer of the series on its printing-surface has a definite and accurate relation to the position of every other transfer of the series on every other printing-surface of the series, and I print from these printing-surfaces in any desired succession and accurately in register according to the definite and accurate relation to each other of the positions of the transfers on the several printing-surfaces attained in the transferring-department. Thus the burden of attaining accurate registry is taken from the printing-department and is thrown onto the transferring-department, and I preferably do this transferring from flat onto rounded or cylindrical and onto continuous cylindrical surfaces. Again, instead of printing each color separately—that is to say, with a separate handling of the paper or edition for each printing and with substantial drying intervals between printings—I print the colors for which separate printing-surfaces have been prepared in approximately—that is, substantially—instantaneous succession—that is to say, with but one handling of the paper or edition for the entire series of printings and without substantial drying intervals between printings and preferably continuously and on the web. The present invention is of apparatus to successfully carry out the printing step of this general method or process, although parts of the invention have of course wider application and more general utility.

In carrying out the general method or process referred to by the apparatus constituting the present invention I print the colors (for which separate printing-surfaces have been prepared) in approximately—that is, substantially—instantaneous succession—that is to say, at one printing operation and with but one handling of the paper or edition for the entire series of printings and without substantial or prolonged drying intervals between printings and preferably continuously and on the web and with a supplying of the colored inks from air-tight receptacles.

The accompanying drawings, forming a part of this specification, show a printing-press which embodies my present improvements.

In the drawings, Figure 1 is a right-hand side elevation of the press, portions thereof being broken away to permit the illustration of other parts of the machine. Fig. 2 is a left-hand side elevation of the same, portions being also broken away for a similar purpose. Fig. 3 is a central vertical section of the same, the section being taken transversely of the machine and looking from the left-hand side. Fig. 4 is a central vertical section taken longitudinally of the machine, looking from the front. Fig. 5 is a front elevation of the machine, with the printing and inking and dam-

pening mechanisms and appurtenances thereof omitted. Fig. 6 is a transverse sectional view of a portion of the machine looking from the left-hand side thereof, showing in elevation one inking and one damping frame, with their appurtenances, and the link-gear connection between the form-cylinder and the main drum, showing in central cross-section one set of inking and damping mechanisms and form-cylinder in operative position, and showing one set in section inside of swinging frame with the inking mechanism swung out to permit the withdrawal of the form-cylinder, and also showing the connection between the damping-frames and the reciprocating wheel for swinging same. Fig. 7 is a plan view of a portion of the machine, showing one set of inking mechanism, form-cylinders, and appurtenances. Fig. 8 is a longitudinal sectional view of a portion of the machine, the section being taken on the line 8 8 of Fig. 6, looking from the front of the machine. Fig. 9 is a longitudinal sectional view of a portion of the same, the section being taken on the line 9 9 of Fig. 6 and looking from the front of the machine. Fig. 10 is a sectional view longitudinally of a portion of the machine, the section being taken on the line 10 10 of Fig. 1 and showing more particularly the grippers and operation thereof by the cams. Fig. 11 is a front detail of one of the grippers, its supporting-bracket, and a small portion of the drum to which it is attached. Fig. 12 is a central vertical section of the same, the section being taken at right angles to the plane of Fig. 11. Fig. 13 is a top view thereof. Fig. 14 is a cross-section on the line 14 14 of Fig. 12. Fig. 15 is a side elevation of a left-side swinging ink-frame and its lifting-plate, the latter being in its lowered position. Fig. 16 is a central cross-section of the same. Fig. 17 is a similar section of a right-side ink-frame. Fig. 18 is a side elevation similar to Fig. 15, but with the lifting-plate in its raised position. Fig. 19 is a section through frame and plate, showing the eccentric for lifting the plate. Fig. 20 is a sectional view taken just inside a right-side swinging ink-frame, looking from the left, the plane of section being on the line 20 20 of Fig. 22. Fig. 21 is a sectional view of a portion of the same on the plane of the line 21 21 of Fig. 22. Fig. 22 is a top view of the parts shown in Fig. 20. Fig. 23 is a horizontal section on the line 23 23 of Fig. 20. Fig. 24 is a vertical section on the line 24 24 of Fig. 20. Fig. 25 is a sectional view from the right, just inside the frame, of a left-side inking and damping frame, showing the train of gears for driving same. Fig. 26 is an end view of Fig. 25, looking in the direction of the arrow 26. Fig. 27 is a top view of Fig. 25. Fig. 28 is a detail view, partly in elevation and partly in central longitudinal section, of a distributing cylinder-head at its left end and of the cams thereof, with their connections, and portions of left-side inking

and damping frames. Fig. 29 is a section on the plane of the line 29 29 of Fig. 28. Fig. 30 is a section on the plane of the line 30 30 ⁷⁰ of Fig. 28. Fig. 31 is a detail of the mechanism for swinging an ink-frame. Fig. 32 is a vertical central section of same, the section being taken at right angles to the plane of Fig. 31. Fig. 33 is a horizontal section on the line 33 33 of Fig. 32. Fig. 34 is a detail section on the line 34 34 of Fig. 15. Fig. 35 is a central section in detail of one end of one of the inking-rollers. Fig. 36 is a similar section of one end of one of the iron riders. ⁸⁰ Fig. 37 is a left-side elevation of the controlling-engine, showing the connections with the rest of the machine. Fig. 38 is a front elevation of same. Fig. 38^a is a detail in side elevation of the levers of the controlling-engine. Figs. 39, 40, and 41 are diagrams showing the relative positions of inking, dampening, printing, and impression surfaces when operating and when not operating. ⁸⁵

For the sake of simplicity I will divide up ⁹⁰ the description of the machine into the several heads—inking devices, dampening devices, printing devices, devices to move or swing each of same, the controlling-engine, and the main drum, and will take up the several heads in the order named. ⁹⁵

The inking devices.—The ink-fountain ⁵⁰ is round or rounded in general shape, as is shown in cross-section in Fig. 3 and in longitudinal section in Fig. 8. It has a supply-nozzle or inlet-pipe, ordinarily closed tightly with a cap, as seen in Fig. 8, one at each end, the nozzle or inlet-pipe being adapted to be secured to any suitable ink-supplying device or system—as, for instance, to the portable ink-supplying device of my pending application, Serial No. 568,795, filed November 13, 1895, or to the ink-supplying system of my pending application, Serial No. 537,593, filed October 30, 1895, renewed May 18, 1899, No. 717,287. This ¹⁰⁰ ink-fountain is liquid-tight and when charged with ink is air-tight, and by reason of this fact and of its peculiar shape it can be conveniently employed in any position with reference to the horizontal (see Fig. 8) and will ¹⁰⁵ operate practically and successfully and with cleanliness. Mounted in the mouth of this ink-fountain is the ink-feeding roller 51, having the usual adjustable discharge-regulating blade or knife 52. The ink-feeding roller ¹¹⁰ 51 is given a step-by-step forward motion either automatically, as hereinafter described, or by hand by means of a removable handpiece 53. To briefly trace the course of the ink from the ink-fountain to the printing-surface, before going into detail as to the many parts and devices connected with this inking apparatus, the ink is by contact transferred from the ink-feeding roller 51 to the ductor-roller 54, from that to the main ink-distributing cylinder ¹¹⁵ 55, then to the intermediate distributing-roller 56, to the large distributing-roller 57, to the middle brass rider 58, to the two middle form-inking rollers 59, then in one di-

rection to the brass rider 60, and then to the form-inking roller 61 and in the other direction to the brass rider 62, and then to the form-inking roller 63 and from the four form-inking rollers to the tubular printing-surface 64. All of these inking parts from 50 to 63, inclusive, are mounted on a swinging frame, called herein the "ink-frame," and which consists of two side frames 65, one on each side 5 of the machine and preferably of the peculiar shape shown in Figs. 20, 15, and 18 and connected by the shaft 66 (to which they are both keyed) and by the connecting or tie rod 67, on which, preferably, the form-inking roller 63 is loosely mounted. This ink-frame is thus 10 solidly and firmly constructed. In the manner to be now described this ink-frame is so mounted or hung as to be capable of swinging toward and from that printing tube or 15 surface which the rollers carried by it ink and so mounted or hung that it is centered with the main ink-distributing roller, which drives the other rollers that it carries. In its swinging it is operated from one point—to wit, 20 from and by the segment of worm-wheel 68—which operation from one point insures certainty of identical movement on both sides or ends of the frame. The method of imparting motion (both automatic and manual) to 25 the segmental worm-wheel 68 will be described below. It might be remarked in this place that the worm-wheel, with its operating-worm, constitutes a powerful device and one that is at the same time self-locking in every position 30 against any independent tendency of the ink-frame to move, as by its own weight.

The four form-inking rollers 61, 59, 59, and 63 are mounted in bearings (in the ink-frame) that are separately adjustable radially toward 40 and from the operative center of the printing-tube 64, as shown in Figs. 15 and 18. These rollers are together brought down into the proper frictional contact with the printing-surface by the lowering of the ink-frame through the means hereinafter described. At such lowering the ink-frame comes down upon two adjustable stops or rests 69, Fig. 7, the front edge of the frame on each side directly under the mountings of the connecting-rod 67 taking against this stop 69. The stop on the left side in Fig. 7 is a screw-bolt (having jam-nut to hold it in adjusted place) mounted in a bracket screwed to the main circular frame of the machine, as indicated 50 at 69 in Figs. 32 and 33, the bracket also encircling and guiding the rod 70, by means of which the ink-frame is raised and lowered. The stop 69 on the right side of Fig. 7 is a similar bolt mounted in a bracket secured to 55 the main circular frame of the machine on that side. The ink-frame-lowering mechanism brings the ink-frame down tightly onto these stops and locks it there, and the stops take the strain and leave the proper frictional contact between the four form-inking rollers and the printing-surface.

The form-inking roller 63 is loosely mounted

on its axis or shaft 67, the latter being secured tightly to the ink-frame at both sides of the frame and constituting a connecting 70 or tie rod of the ink-frame itself. This enables me to dispense with the use of separate tie-rods or strengthening-rods.

The first three form-inking rollers 61, 59, and 59 are constructed at one end as shown 75 in Fig. 35, in order that they may be readily removable from their mountings in the ink-frame. The end of the roller-shaft (the part that is seated in and turns in the bearings) is a rod 75, so mounted in the end of the roller 80 as to be capable of a limited motion lengthwise of the roller. It has a spring 76, exerting constant pressure upon the rod to force it outwardly to its normal operative position, which position is shown in the drawings, Fig. 85 35, and it also has a thumb-piece or straining-piece 77, by which it may be pressed inwardly against the spring. When so pressed inwardly, the roller is free of its mountings and can be lifted out of the machine. 90

The connecting-rod 67, which carries the fourth form-inking roller 63 loosely mounted on it, is constructed at one end in the manner indicated in Fig. 36, although that figure is a section of one end of one of the brass 95 riders. The part of the rod that projects into and turns in the bearings is a separable part 78, which can be screwed into and unscrewed from the rest of the rod or roller. In this way this rod 67 is removable from the ink-frame, and with it the roller 63, that it carries. 100

The two outer brass riders 60 and 62 oscillate back and forth in the direction of their length. The middle brass rider 58 does not oscillate. This oscillation of the outer brass riders is about once for every six revolutions. It is brought about from the revolution of the middle brass rider, as follows: The mechanism is shown at the right in Fig. 7 and in detail in Figs. 20 to 24. The shaft of the middle brass rider 58 has a worm 71 near one end, which drives a spur-wheel 72, mounted in a bracket of the ink-frame. This spur-wheel 72 carries an eccentric-pin 73, which projects down into a slot in one arm of the double-acting lever 74. This lever is mounted centrally in another bracket of the ink-frame. One end of the lever works in a groove between collars fast to the shaft of the brass rider 60 and the other end of the lever works 110 in a similar groove in the shaft of the brass rider 62. The revolution of the middle brass rider 58 thus produces longitudinal reciprocation of the two brass riders 60 and 62 and about one such reciprocation for every eight 115 revolutions of the middle brass rider. The three brass riders, 60, 58, and 62 have at one end the construction shown in section in Fig. 36, which figure is a sectional view of one end of one of those brass riders. The part 78, which 120 projects into and turns in the bearings in the ink-frame, is separable from the rest of the roller or rider, being tightly screwed into the end of the same, as shown. This construc- 125 130

tion is more permanent and simple and compact for a roller end than that shown in Fig. 35, and still is removable. The construction shown in Fig. 35 makes the roller more conveniently removable and replaceable, and hence is used upon the rollers that are likely to more frequently require removing and replacing where the surrounding parts of the press permit. The two distributing-rollers 56 and 57 have the construction shown in Fig. 35, with the spring-shaft end 75 and the thumb-piece 77, permitting ready and convenient removal and replacement.

The ink-distributing rollers 56 and 57 and the brass riders 58, 60, and 62 are positively driven from and with the main ink-distributing cylinder 55. The details of this driving mechanism are shown in Figs. 25, 26, and 27.

79 is a gear-wheel that is fast on the hub of the main ink-distributing cylinder and revolves positively with that cylinder. It drives gear-wheel 80, which is fast on the shaft of roller 56. This drives gear-wheel 81 on the shaft of roller 57, which in turn drives gear-wheel 82 on the shaft of middle brass rider 58. This drives two gear-wheels, on one side 83, which runs loose on a short shaft projecting from the ink-frame, and on the other side 84, which runs loose on another short shaft projecting from the ink-frame. Gear-wheel 83 drives gear-wheel 85, which is fast on the shaft of the brass rider 62, and gear-wheel 84 drives gear-wheel 86, which is on the shaft of the brass rider 60.

To lift the several inking-rollers out of contact with one another when the press is not operating and to secure and insure the proper and a uniform contact between adjacent rollers when the press is operating, I provide and employ on the ink-frame two lifting (or, more properly, lifting and depressing) plates 100, one at each side of the machine. These lifting-plates are well shown in Figs. 15, 16, 17, 18, and 19. They are arranged on the outside of each side frame of the ink-frame and are reciprocable on said frame, two bolts and slides made fast to the ink-frame sliding in two guiding-slots 87 in the lifting-plate. The lifting-plates are reciprocated by means of two eccentrics 88, carried on and fast to one and the same shaft 89, one at one end and the other near the other end of the shaft. The shaft is squared at one end, 90, whereby it may be turned by any suitable crank or key and the lifting-plates thus lifted or depressed. The eccentrics 88 are encircled by suitable collars 91, secured to the lifting-plates and properly shaped—that is to say, elongated horizontally—so as to transform the revolving motion of the eccentrics into an up-and-down motion of the lifting-plates. The eccentric at one end of the shaft carries a radially-enlarged eccentric plate extending out over the outer face or side of the collar 91 to serve as a guiding and steadyng part for the collar, and also carries a segmental stop 92 on the inner face or side of the collar,

which at the end of each half-revolution of the eccentric to and fro takes against first one end and then the other end of an inward segmental projection 93 of the collar 91. This acts as a stop, limiting the motion of the eccentric between these two extremes and furnishing a simple means of knowing when the full up or down stroke of the lifting-plates 75 has been attained and of insuring the return of the lifting-plates always to the same identical position when lowering the rollers into operative position. The lifting-plates are connected with the five several rollers under 80 consideration in such a manner that on the lifting of the lifting-plates said rollers are positively moved out of operative position, the large and uppermost ink-distributing roller 57 beginning first to rise out of operative position, then and after a short interval of time the ink-roller 56, and finally and after another short interval the three brass riders 60, 58, and 62, each roller moving in the longitudinal line of the slideway in which it is mounted in the ink-frame, and all continuing to move until the eccentrics have reached the limit of their movement, and, further, the lifting-plates are so connected to the several rollers that on the lowering of the lifting-plates 95 the rollers will reach their lowest positions in the reverse order—namely, the three brass riders first, then the small ink-roller 56, and, lastly, the large ink-roller 57; but at the last of the downward motion of the lifting-plate 100 all five of the rollers—to wit, the three brass riders, the large distributing-roller 57, and the small distributing-roller 56—are positively forced down to exact operative position, the first four directly by the lifting-plate 105 or its parts and the fifth through the fourth. The parts attaining this positive downward thrust of the rollers at the last end of the stroke into exact operative position are separately adjustable. The said connections between lifting-plate and rollers are as follows: Take first the large distributing-roller 57. The sliding box 94, which constitutes its bearings and which slides in a slightly-inclined slideway in the ink-frame 65, (angularly inclined with respect to the guiding-slots 87), is extended laterally into and through a square opening or recess 95 in the lifting-plate, the bottom of the box or roller bearings 94 resting on or near the bottom of the opening or recess 95 when both roller and lifting-plate are in their lowest positions. Any substantial lifting of the lifting-plate raises the box 94 in its slideway in the ink-frame, the box coincidentally sliding across the bottom of the opening 95 from left to right in Fig. 15. Above the box or bearings 94 and secured in the lifting-frame or in a suitable projecting lug of the same are adjustable pressure devices 96, shown as two set-screws 110 with jam-nuts, their lower ends taking against a loose washer or buffer-piece resting on the top of the box 94, the buffer-piece being free to move up and down in the opening 95 in

the lifting-frame, where it is held from falling out by its forked ends grasping the sides of the opening. When the lifting-plate is lowered, the pressure devices 96 positively force the box 94 down its slideway in the ink-frame to its lowest and operative position. Their adjustment determines that position accurately. The opening or recess 95 is wider than the extended sliding box 94 to permit of the necessary sidewise motion of the sliding box in the recess in taking the up-and-down motion imparted to it by the lifting-plate, the cutting off of the corners of the laterally-extended sliding box or bearings contributing to this end.

The small distributing-roller 56 is connected with the lifting-plate in the following manner: It is mounted in bearings that constitute a sliding box sliding in slideways in the ink-frame toward and from the main ink-distributing cylinder 55. The lateral extension of this sliding box enters a recess in a link 97, which link is pivoted at 98 to the lifting-plate. The recess in the link 97 is elongated, so that when the lifting-plate begins to rise from its lowest position (that shown, for instance, in Fig. 15) there is considerable upward motion of the plate and link before the bottom of the recess in the link strikes the bottom of the sliding box and so before the roller 56 begins to move upwardly through its slideways in the ink-frame. This accomplishes the ultimate separation of the three rollers 57, 56, and 55 from one another.

The three brass riders 60, 58, and 62 are connected with the lifting-plate in a manner substantially similar to what has been described in connection with roller 57. The square recesses or openings in the lifting-frame are, however, more elongated vertically downward, so as to occasion considerable lost motion of the plate in lifting before the riders begin to rise, substantially as in the case of roller 56 and with a similar purpose and effect, and the apparatus for adjusting the downward pressure of the lifting-plate at the end of its downward stroke is slightly different in the case of riders 60 and 62 in that the screw-bolts screw into two bosses or swells projecting from the lifting-plate and carry a yoke 99 between them, which yoke constitutes the upper or outer end or wall of the recess and takes against the top of the extension of the sliding box carrying the roller, and so presses the roller down to its proper contacts in use.

Fig. 15 shows the lifting-plate in its lowest position when the pressure functions of the lifting-plate are being exerted to force and hold the several rollers positively to their proper operative contacts. That figure also indicates the lost motion that will occur in the case of roller 56 and the three brass riders when the lifting-plate is lifted—namely, by 65 the space existing in each case between the bottom of the opening or recess in the lifting-plate or in the link attached to it and the bot-

tom of the extended sliding box. Fig. 18 shows the lifting-plate in its highest position. At such time all five of the rollers in question are out of operative position and are carried by the lifting-plates, being held out of contact by one another and also out of contact with the main ink-distributing cylinder 55 on the one side and out of contact with the four form-inking rollers 61 59 59 63 on the other side. It is intended that the rollers shall be moved into this position whenever the press is not operating.

The main ink-distributing cylinder 55 runs loosely on the shaft 66. The two ink side frames 65 are keyed fast to that shaft. The shaft only moves when the ink-frame moves. This is an important improvement in construction. The ink-frame is operated from one side only, the shaft 66 being strong enough to carry up both sides. Thus both sides of the ink-frame move together without the different lost motion of two different trains of moving mechanism differently affecting the two sides.

The main ink-distributing cylinder 55 has a hub at each end, as is shown in Fig. 8. At the right-hand end of the hub, on the right, as shown in Fig. 8, there is a gear-wheel 101, 95 fast on the hub by which this main ink-distributing cylinder is driven, the gears to that end meshing with an intermediate gear-wheel 102, mounted on a bracket 103, bolted to the main circular frame of the press on one side, 100 the gear-wheel 102 meshing with a gear or rack 104 on the main impression drum or cylinder of the press. The gear-wheel 101 has an internal cam-groove on its outer face or side by means of which and the connecting parts, to be described, the ductor ink-roller 54 is reciprocated at one end to and fro in its slideway from the ink-feeding roller 51 in the mouth of the ink-fountain to the main ink-distributing cylinder 55. At the 110 left-hand end of the hub of cylinder 55, on the left, as shown in Fig. 8, is the gear-wheel 79, fast on the hub, which gear-wheel drives the inking-rollers, as hereinbefore described, and the dampening-rollers, as hereinafter described, all as shown in detail in Figs. 25, 26, and 27. This gear-wheel 79 has two internal cam-grooves, the one on the outer face or side reciprocating the other end of the ductor ink-roller 54 and the one on the inner face or side 115 reciprocating the water-supply roller toward and from the brass rider of the group of dampening-rollers, as hereinafter described.

The ductor ink-roller 54 is reciprocated, as shown in detail in Figs. 28, 29, and 30, where 125 79 represents a section of the gear-wheel on the line 30 30 of Fig. 28, showing the cam-groove 105, the roller-pin 106 working in the cam-groove and mounted on and carrying to and fro the slide 107, moving in the slideways 108 of the ink-frame and carrying the mountings or bearings 109 of the ductor ink-roller. This mechanism is duplicated at the other side of the press, where the gear-wheel 101 has a cor-

responding external cam-groove 105 on its outer face or side. (See Fig. 8.) The ductor-roller is adjustable in the slides 107, which carry it, whereby the contact of said roller with the feeding-roller on one side and with the main ink-distributing cylinder on the other side is reliably regulated.

The ink-feeding roller 51 in the mouth of the ink-fountain is operated as follows: The intermediate gear-wheel 102, Fig. 8, at right, has an eccentric hub which is encircled by a collar 110, held on as shown, and having an inwardly projecting or depending arm in which a short horizontal rod 111 is bolted fast, the horizontal rod projecting through a slot in the main circular frame of the press, to the outside of the same, where a sliding rod 112 is pivoted to it, the rod being pivoted at its upper or outer end to a link 113, which link is at its outer end adjustably secured to an ordinary pawl-and-ratchet mechanism secured to the ink-feeding roller. Thus the continuous rotation of the gear-wheel 102 is transformed into a reciprocation of the rod 112, and that into a step-by-step forward rotation of the ink-feeding roller 51. The adjustability of the connection of the link 113 with the pawl-and-ratchet mechanism is provided in the capacity to secure the link to the ratchet-lever at a point farther out from or in nearer to the fulcrum of that lever. A slideway 114, Fig. 1, is provided for that purpose. To secure the end of the link farther out in the slideway will reduce the angular rotative advance of the ink-feeding roller for each reciprocation of the sliding rod 112, and vice versa.

As stated before, there is a hand attachment to be used whenever desired—namely, an ordinary hand-ratchet 53, Fig. 8, to be applied on the inside of the pawl-and-ratchet mechanism.

This inking mechanism is repeated for each and every printing tube or surface of the press.

The dampening devices.—The dampening mechanism for each printing tube or surface is carried on a damping-frame 115, Figs. 6, 8, 28, and 29, which damping-frame is so hung as to be capable of swinging toward and from the printing tube or surface that its rollers dampen, and so hung as to be centered with the main ink-distributing cylinder, from or with which the dampening-rollers carried by it are driven. At the left, as shown in Fig. 8, the damping-frame has a collar 116 loosely encircling the shaft 66, and at the right it has a collar 117 loosely encircling a hub 118 on the bracket 103 of the main circular frame, this hub 118 itself loosely encircling the hub of the main ink-distributing cylinder 55. The damping-frame carries a water-supply roller 119, a brass rider 120, and two form-dampening rollers 121 and 122. The brass rider 120 and one of the form-dampening rollers 121 are constructed at one end as shown in Fig. 36 and heretofore de-

scribed. The other form-dampening roller 122 is constructed at one end as shown in Fig. 35. All three rollers 120, 121, and 122 are mounted or carried in boxes or bearings that are adjustably fixed in slideways or slots in the damping-frame 115. This is shown in Fig. 6. Internal adjusting and fixing bolts and jam-nuts are used (internal with reference to the slideways) where external ones cannot be used. The water-supply roller 119 in its internal construction is shown in a separate application heretofore filed by me—to wit, Serial No. 685,765, filed July 12, 1898—and such construction therefore need not be

here further described except to say that the roller has an axial water-inlet through the journal at one end and a controllable circumferential water-discharge and is kept supplied with fresh water through a source of continuous supply—as, for instance, by the system shown in my pending application, Serial No. 717,287, filed May 18, 1899—connecting by a flexible pipe with the interior of the hollow squared end angle piece or coupling 123 of the water-inlet that leads into the interior of the roller. This water-supply roller 119 is removably mounted in the dampening-frame as follows: One side 124 of the slideways of the damping-frame in which the water-supply roller reciprocates in use is hinged at one end and when closed is held closed by a stout spring-catch 125. (See Fig. 6 at right, also Fig. 29.) The carrying-arms 137, herein-after described, are open forks at their holding ends. (See Figs. 6 and 29.) Also the link 133, herein-after described, has a hinged collar at its grasping end which can be unlatched and opened. (See Fig. 6 at left and Fig. 2 at right.) The water-supply roller can thus be lifted out bodily from the press.

The water-supply roller 119 and the brass rider 120 are driven positively with one of the main ink-distributing rollers. The same gear-wheel 79 on the hub of the main ink-distributing cylinder (see left of Fig. 8) that drives the inking-rollers also drives these damping-rollers. That gear-wheel 79 (see Figs. 25 and 26) meshes with and drives a small gear-wheel 126, loosely mounted on a shaft of the damping-frame immediately inside the frame at the left-hand side of the press, as seen in Fig. 8. This meshes with and drives a gear-wheel 127, mounted on the shaft of the upper or outer form-dampening roller 121, which in turn meshes with and drives a gear-wheel 128, fast on the shaft of the brass rider 120, and so drives that brass rider. The gear-wheel 127 is fast with another gear-wheel 129 on the same shaft, but outside of the damping-frame. This gear-wheel 129 meshes with and drives a gear-wheel 130, and the latter meshes with and drives gear-wheel 131, which is fast to the water-supply roller, and thus the water-supply roller is driven. The gear-wheel 130, intermediate in this chain of gear-wheels between 129 and 131, is carried loosely on the connect-

ing-pivot of a chain of two links 132 and 133, the one of which, 132, is at its other end loosely carried on the shaft or hub of the gear-wheel 129, and the other of which, 133, is at its other end loosely carried on the shaft of the gear-wheel 131 and detachably carried, as already stated, having to that end a split and hinged collar to operatively encircle the shaft and held closed by a spring-catch, as shown in Figs. 2 and 6. These chains of links and gear-wheels on the outside of the damping-frame by which the water-supply roller is rotated are shown at the left in Fig. 6 and at the upper part of Fig. 2. They permit reciprocation of the water-supply roller 119 to and from the brass rider 120 without interrupting the rotation of the water-supply roller. When it is desired to remove the water-supply roller from the press, the hinged collar should be unlatched and opened.

The water-supply roller 119 is reciprocated to and from the brass rider 120 in the following manner: The power comes from the main ink-distributing cylinder that drives the water-supply roller and the brass rider. The gear-wheel 79 of that cylinder has an internal cam-groove or eccentric groove 134 on the inner side or face of the wheel. (See Figs. 8, 28, and 29.) In this groove is a roller 135, loosely mounted on a pin fixed in and forming part of a forked guiding link or arm 136 at the crotch of the fork, the tines of the fork grasping loosely the hub of the main ink-distributing cylinder between them and being themselves held loosely between collars on that hub. The forked guiding link or arm 136 is loosely pivoted at its lower or inner end to one of the roller-carrying lever-arms 137. This arm 137 is keyed on the shaft 138 of the damping-frame (the shaft on which gear-wheel 126 is loosely mounted) and has its duplicate carrying-arm 137, at the other end of the shaft, also keyed on the shaft, and the moving ends of these two carrying-arms 137 carry in a suitable open-fork bearing the shaft of the water-supply roller 119, one at each end of that shaft. As the main ink-distributing cylinder revolves the roller-pin 135, guiding-link 136, and lever-arms 137 reciprocate, and the water-supply roller is thereby caused to reciprocate up and down the slideways in the damping-frame, heretofore referred to, and so to and from the brass rider. The open forks in the carrying-levers 137 permit the motion of the roller-bearings up and down the slideways and also permit, as stated, the removing of the roller from the press when the sides 124 of the slideways are unfastened and swung out. The connection of the forked guiding link or arm 136 with the carrying lever-arm 137 is adjustable and in this way: There is an elongated slot in the latter (shown in dotted lines in Fig. 29) in any part of the length of which the end of the arm 136 can be pivotally secured. This adjustability permits the accurate securing of the proper contact-pressure between the water-supply roller

and the brass rider. The details of the method shown of pivotally connecting arm 136 and lever 137 are these: A bolt passing through both has a large head outside of the carrying-lever and a central enlarged bushing between the lever and the arm, this bushing being on the side of the arm 136 reduced to a hub, which passes loosely through the arm 136 and against the end of which hub the washer under the nut on the inner end of the bolt takes and jams on tightening instead of jamming and tightening on the arm 136. This jams and tightens the lever 137 and the bolt, nut, and bushing together and leaves the arm 136 free to turn loosely on the hub of the bushing. As already stated, there is a similar roller-carrying arm 137 at the other side of the press carrying the other end of shaft of the water-supply roller. These two arms are both keyed to one and the same shaft 138, which is loosely mounted in the damping-frame, and so when one of them is reciprocated by the arm 136 both are reciprocated and both ends of the water-supply roller move reliably together.

The water is introduced into the water-supply roller through a pipe the flexibility of which near the end of the shaft of the roller permits of the necessary reciprocating motions of the roller. To prevent the coupling or connection with the shaft turning or loosening with the combined reciprocating and revolving motions of the water-supply-roller, the hollow angle piece or coupling connecting the hollow journal of the roller with the flexible water-supply pipe is squared externally, (123,) and there is a locking-guide 139 (see Fig. 6 at the left) fixed to the damping-frame, having a properly-extended locking-face which acts as a guide for the angle-piece 123 in its reciprocations, one squared side of the angle-piece sliding up and down the extended face of the locking-guide and being thereby locked—that is, kept from turning. These dampening mechanisms are repeated for each separate printing-surface of the press, the inking mechanisms of one printing-surface and the dampening mechanisms of the next adjacent printing-surface being grouped together and driven together.

The printing devices.—The printing-surfaces are in the form of thin tubes or cylinders removable from their supporting parts or form-cylinders and presenting each a continuous external printing-surface. The details of their internal construction and of their combination with their supporting parts form the subject-matter of two applications heretofore filed by me—viz., Serial No. 537,582, filed February 7, 1895, and Serial No. 568,178, filed November 7, 1895, renewed January 20, 1899, Serial No. 702,945. Briefly described, 218 is the external removable and replaceable hollow printing-surface, and 219 is the internal form-support or form-cylinder. (See Figs. 6 and 9.) The hollow printing-surface is slipped on and off of the left end of the form-

cylinder, as the same is seen in Figs. 4, 7, and 9. It is slipped on until it strikes against an adjustable shoulder 220 and is held there by an adjustable clamp 221. Further details as to the internal construction of the printing-surfaces 64 and their several adjustabilities need not here be given. The form-supports, with their carrying-shafts and sliding boxes, are removable from their mountings in the press, as hereinafter described. In removing the printing-tubes and replacing them such apparatus may be conveniently used as is shown in my applications heretofore filed, Serial No. 552,641, filed June 13, 1895, renewed July 12, 1898, Serial No. 685,764, and Serial No. 578,841, filed February 11, 1896, renewed July 12, 1898, Serial No. 685,766.

The printing-surfaces 64 are driven in the following manner, reference being especially had to Figs. 4, 5, 6, and 9 of the drawings in this connection: On one side of the press, near the right-hand edge of the impression-drum, as shown in Figs. 4, 5, and 9, is a gear 140, which revolves with the drum, being secured thereto, and which meshes directly with a gear-wheel 141, keyed on the shaft of the printing-surface 64 when that shaft and printing-surface are down in operative printing position. At the other side of the press and also revolving with the drum because solidly secured thereto is another gear 142 of lesser diameter than the gear 140. This, through a chain of two intermediate gear-wheels 143 and 144, drives a gear-wheel 145, which is fast on the shaft of the printing-tube 64. The gear-wheel 143 is loosely mounted on a short shaft bolted to the main circular frame of the press. A chain of two links 146 and 147 are pivoted together at their inner ends, and are at their respective outer ends pivotally connected to the short shaft just referred to as carrying the gear-wheel 143 and to the shaft of the printing-surface 64, the center pivot that connects the two links carrying the gear-wheel 144. The relative sizes of gears 140 and 141 and of gears 142, 143, 144, and 145 are such as to give the same angular speed at the printing-surface shaft. The effect and operation of the driving mechanism on the left, as described—that is to say, the mechanism involving the chain of gears and the chain of links—are to positively drive the printing-surface with and from the impression-drum when it is raised out of printing contact with the drum, as well as when it is lowered into such contact, and thus the exact and registering relationship of each one of a whole series of printing-surfaces with one and the same impression-drum (and hence with each other) is accurately and exactly and inevitably maintained however often or however much the said printing-surfaces may either collectively or individually be raised or lowered—that is to say, be moved from or toward the impression-surface. Thus the printing-surface when printing is simultaneously and positively driven at both ends

of its shaft with and from one and the same prime motor, the impression-drum, and when raised out of printing contact it continues to be positively driven from the same motor, so that when lowered again into printing contact its former registering relationship with that prime motor—to wit, with the impression-surface—is exactly and reliably restored—that is to say, this registering relationship is automatically maintained despite raisings and lowerings out of and into contact, and this in conjunction with direct positive driving during printing. Again, the gear-wheel 145 near one end of the printing-tube shaft is less in diameter than the gear-wheel 141 near the other end, and this results in the practical convenience that the printing-tubes 218, being larger in internal diameter than the gear-wheels 145, (though not larger than the gear-wheels 141,) can be slipped on and off over this smaller gear-wheel, and thus both gear-wheels can be made permanently fast on the shaft. The upper or outer link 147 is removably connected to the shaft of the printing-tube 64 by a hinged collar at its end encircling the shaft and locked thereon by a nut screwing onto a bolt formed by the two parts of this collar when closed. The gear-wheels 140 and 141 should be marked with respect to each other, and gear-wheels 144 and 145 may also be marked with respect to each other, so that after being unmeshed (as when opening the collar of the link 147 and lifting the printing-tube shaft out of the press for any purpose) they may be meshed again in the same identical meshing relationship to each other—that is to say, a given marked tooth of the one always entering a given marked recess of the other. The chain of links has a stop 148 adapted to take against a suitable stop on the bracket of the frame to hold the links, and so the chain of gear-wheels, approximately in place when uncollared from and so unsupported by the shaft of the printing-tube.

The controlling-engine generally.—It is necessary in the operation of the press to move some parts of the mechanism of the press into and out of operative position—as, for example, the series of printing-surfaces, the inking mechanisms, and the damping mechanisms. To move the entire series of printing-surfaces out of or into contact with the impression-surface, also to move the inking mechanisms out of or into contact with the printing-surfaces by swinging the ink-frames, also to move the dampening mechanisms out of or into contact with the printing-surfaces by swinging the damping-frames or generally to move any part of the press into or out of operative position, I have devised new and improved mechanisms to be now described. These mechanisms may be used independently of each other and manually, if desired; but I prefer to employ them in connection with the normal running or operation of the press in printing, although I prefer to employ

them at will and independently of the printing operation of the drum, and I have devised a mechanism to that end which I call the "controlling-engine," in connection with the movements of the printing-surfaces, inking mechanisms, and dampening mechanism referred to above as shown herein. The purpose of this controlling-engine is this: When it is desired to stop the press, the controlling-engine shifts some of the power to the mechanisms for raising the printing-surfaces, for swinging the ink-frames away from the printing-surfaces, and for swinging the damping-frames away from the printing-surfaces, and then the power is turned off altogether. In starting the press the controlling-engine shifts some of the power to said mechanisms, but in the reverse direction, and thereby swings the inking and damping frames in onto the printing-surfaces and the latter in onto the impression-surface, the impression surface or drum and all the parts meantime revolving.

Device to move printing-surfaces.—The printing tubes or surfaces are moved toward and from the impression drum or surface in the following manner: The shaft 149, Figs. 2, 4, and 5, conveys the power from the controlling-engine or from any other desired motor to do the work. It has two small gear-wheels 150 at each side of the press, each meshing with a segmental gear on the long arm of a lever 151. This lever, at the top, encircles the hub, which constitutes the bearings of the main drum and is centered therewith and free to turn thereon. It is securely bolted to a disk or plate similarly centered and carried, and there are in said disk a series of radial slots 152, one for each printing-surface of the press. In each of these slots 152 is the extension of a pin 153, being the center pin of a toggle-lever consisting of the said connecting-pin and the two links 154 and 155, pivotally connected by the same. The outer end of the outer link 154 is pivoted to the main circular frame of the press, and the inner end of the inner link 155 is pivoted to the inner end of a pressure-bar 156, the latter carrying at its outer end the sliding box 157, sliding in a slot in the main circular frame of the press and constituting the bearings of the shaft of the printing-surface 64. The pressure-bar 156 moves in suitable guides in the main circular frame of the machine, and the sliding box 157 is adjustably mounted upon it, the details of the connection of pressure-bar, sliding box, and printing-surface being set out in applications heretofore filed by me, and particularly Serial No. 518,015, filed July 19, 1894, renewed May 27, 1899, Serial No. 718,570, and Serial No. 568,795, filed November 13, 1895. Briefly described, the pressure-bar 156 adjustably carries the printing-surface 64 and connected parts through the sliding boxes 157, having to that end an adjusting-nut 222 (see Fig. 9) to adjust the position of the sliding box on the pressure-bar, a jam-nut 223 to lock 222 in place, and a holding-nut

224 to hold the sliding box in place. The sliding box 157 has an adjustable internal core 225, in which the shaft of the printing-surface is carried to adjust the longitudinal position of the printing-surface, as for wear. By the mechanism described a revolving of the shaft 149 produces a slow but very powerful revolving or shifting motion of the disk 75 or plate having the slots 152, and a revolving of that disk or revolvable shifting plate in one direction strengthens the toggle-levers 154 155 and so brings down the printing-surfaces onto the impression-surface and a revolving in the other direction raises the printing-surfaces from the impression-surface, and the former operation of straightening the toggle-levers produces the slower motion of the two in the pressure-bars 156, 80 but gives the greater power in that motion, as is needful to simultaneously attain the proper printing-pressure contacts of a whole series of printing-surfaces that are heavy and arranged in all sorts of positions with 85 reference to the operation of gravity and that call for the attainment in the aggregate of many tons of inward pressure along the printing-lines. The parts described are duplicated on each side of the press, as shown in 90 the drawings.

When it is desired to take any one of the printing-surfaces out of the press, it is raised as far as may be by the operation of the mechanisms above described. The link 147 100 is then disconnected from the shaft of the printing-surface by unlocking and swinging open the hinged collar that is at its outer end and the holding-nuts 224 on the top of the pressure-bars 156 are unscrewed. The 105 printing-surface shaft can then be grasped and moved radially out from the machine, together with the sliding boxes 157 and the parts carried by said shaft, the inking mechanism being first swung up out of the way, 110 as illustrated in Fig. 41 at the right and as hereinafter described. When so raised, the tubular printing-surface 218 will slip over the gear-wheel 145 and the sliding box 157 (or the latter may be first removed) and so 115 wholly off of the form-cylinder 219, being first unclamped at 221.

Devices to move ink-frames.—The ink-frames 65 are simultaneously moved toward and from the printing-surfaces in the following manner: The controlling-engine, herein-after described, drives a shaft 158 at the left of the press, as seen in Fig. 5, or that shaft might be otherwise driven, if desired. This has a beveled gear-wheel at its upper end 120 meshing with a beveled gear-wheel on the end of a short horizontal shaft 159, which passes through the frame of the machine and which has another beveled gear at its inner end. This meshes with a beveled gear at the 125 lower end of a shaft 160, which shaft has a worm midway of its length and is mounted in brackets bolted to the main circular frame. The worm of this worm-shaft drives a large cen-

trial worm-wheel 161, which is loosely mounted on the hub of the frame which constitutes the bearings for the main drum. This wheel 161 has on its outer side or face a beveled gear 5 which drives a series of small beveled gear-wheels (one for each ink-frame of the press) on the inner ends of a series of radial rods 70. Each rod 70 has a bearing for its inner end in the hub constituting the bearings of the main 10 drum, as indicated in Fig. 5, and a central bearing in a bracket of the main circular frame, as shown at the bottom of Fig. 32 and as indicated at 70 in Fig. 33. Each rod 70 has near its outer end a worm 162, with which 15 it is detachably connected, as hereinafter described. The worm 162 has bearings in a bracket of the main circular frame and meshes with the segmental worm-wheel 68, which is secured to the ink-frame 65 on one side of the 20 press. As stated heretofore, the frame 65 at one side of the press, with its segmental worm-wheel 68, is keyed to the shaft 66, and the frame 65 at the other side of the press is similarly keyed to the same shaft. By the train 25 of mechanisms described the entire series of ink-frames are raised or lowered from or toward their respective printing-surfaces and this simultaneously and from the controlling-engine and through a central driving mechanism--to wit, wheel 161 and connected parts. The limit of the motion toward the printing-surfaces is determined by the adjustment of the controlling-engine and of connecting parts, as hereinafter described, and in connection therewith also by the adjustment of 30 the adjustable stops 69, the two mechanisms being so adjusted with respect to each other that just the proper contact-pressure between the form-inking rollers 61, 59, 59, and 63 and 35 the printing-surface 64 is reliably and uniformly and automatically brought about. The limit of the simultaneous outward movement of the ink-frames is found in the controlling-engine. In practice it is not very 40 great, but is enough to give a clear space of a quarter of an inch between the printing-surface when the latter is moved outwardly to its farthest point by the controlling-engine and the then nearest of the four form-inking 45 rollers. Fig. 39 shows the printing-surfaces and the inking-frames moved inwardly into operative position by the controlling-engine. Fig. 40 shows the printing-surfaces raised by the controlling-engine from the impression-drum and the inking-frames raised by the controlling-engine from the printing-surfaces. Fig. 6 shows the three printing-surfaces moved 50 inwardly into operative position by the controlling-engine and two of the three inking-frames at the left so moved inwardly by the 55 controlling-engine. To move any one of the inking-frames farther outwardly, as in order to get at and remove or replace a printing-surface and its supporting parts, I have devised 60 the following mechanism: Each worm 162 is to that end made detachable from the radial rod 70, and so becomes, with its connected

parts, a separate swinging mechanism to swing its separate ink-frame, and for that purpose is provided with an appliance whereby it can 70 be turned separately and so independently of the other ink-frames. The worm 162 is cut in a sleeve that loosely fits the rod 70. At its upper end it is encircled by a cap 163, having two jam or set screws, as shown in Fig. 32, 75 which are tightened, and so bind the worm and the cap securely together. The cap in its upper end has a square internal recess, in which slides a square dog or lock 164, which is controlled in its up-and-down position by the 80 screw bolt or key 165, which screw bolt or key turns freely in the square dog or lock, but travels up and down in the screw-threaded upper end of the cap. This key 165 has a squared head, as shown, whereby it can be screwed as 85 desired and the dog or lock 164 raised or lowered within the cap 163. The upper enlarged end of the rod 70 (the enlargement serving as a retaining-collar) has a similar squared recess matching that of the cap and directly 90 under it. Into this squared recess in the rod 70 the dog or lock 164 partly enters when the bolt or key 165 is screwed down, and by so doing it locks the rod 70 and the cap 163 (and so the worm 162) rotatively together. An 95 unscrewing of the bolt or key 165 raises the dog or lock wholly out of the recess in the rod 70, and by so doing the parts are unlocked, after which no rotative motion of the rod 70 would rotate the worm, and vice versa. 100 To rotate the worm 162 at such times, I provide a beveled gear on the outer face of the cap 163 and a beveled gear-wheel meshing with it and carried on the end of the short driving-shaft 166, mounted in the main 105 circular frame of the press and having a squared end by which to turn it as much as desired by a suitable crank or wrench. Figs. 6 and 41 show one of the ink-frames (at the right in each case) raised by the hand-shaft 110 166, as for the purpose of lifting the printing-surface and its shaft out of the machine. The detachability of the worm and cap from the rod 70 furnishes a means of adjustment between those parts, for the cap 163 may be 115 unlocked from the rod 70 by the raising of the dog or lock and then be given one or more quarter-turns by means of the shaft 166 and then locked by the lowering of the dog. If finer adjustments were desirable, the dog and 120 the recesses in which it works might be polygons of more sides than a square--e. g., octagons or duodecagons, or the like. Thus each separate swinging mechanism for each separate ink-frame is adjustable with respect to 125 the central driving mechanism for simultaneously swinging all of the ink-frames.

Devices to move damping-frames.—To move the damping-frames simultaneously toward and from the printing-surfaces, I have devised the following apparatus: The controlling-engine, as hereinafter described, drives the horizontal shaft 167, Fig. 5, or it might, if preferred, be independently driven from

some other prime motor. The shaft has a beveled gear-wheel at one end, which meshes with a beveled gear-wheel on shaft 168. The latter has a worm at its upper end, which drives a worm-wheel on the outer end of a short horizontal shaft 169. On the inner end of this shaft is an eccentric 170, (see Fig. 3,) working in a slideway in a wheel 171, the wheel being loosely mounted on the hub that constitutes the bearings of the main drum. (See Fig. 4.) The wheel has a series of inwardly-projecting pins 172, one for each damping-frame. Each of these pins 172 works in a slideway in the long arm 173 of a rocking lever which is fast to a rock-shaft, being a sleeve 174, loosely carried on a tie-rod 45 of the main circular frames of the press. (See Figs. 6 and 8.) The short arms 175 of the rocking lever are also fast to the sleeve 174 and are two in number in each case, one at one side of the press and one at the other side, and at their outer or moving ends the two in each case are each loosely secured to a link 176, which is pivoted to the binding-rod 177 of the damping-frame 115. The revolving of the eccentric 170 rotatively oscillates the wheel 171, thereby oscillating simultaneously the long arms 173 and so the short arms 175 of the series of levers and so oscillating the damping-frames toward and from the printing-surfaces and the two form-dampening rollers 121 and 122 into and out of contact with the printing-surfaces 64. The links 176, connecting the short arms 175 of the rocking levers with the tie-rod 177 of the damping-frame, are adjustable as to length, being made in two pieces or lengths united or connected together by a suitable nut in any well-known way, as indicated in Figs. 6 and 3 of the drawings.

Fig. 6 shows at the left and center the relative positions of the inking, dampening, printing, and impression surfaces when the press is ready to be at work printing, and at the right it shows those same positions, except that the ink-frame at that point has been raised by the hand driving-shaft 166—as, for instance, to get at the printing-surface. Fig. 39 also shows the relative positions of the parts when the press is at work printing. Fig. 40 shows the relative positions of the parts when the press is out of operation and at rest, the said several surfaces having been all automatically separated from one another by the action of the controlling-engine and connected parts and the separate inking-rollers having been also separated from each other by the raising of the lifting-plates. Fig. 41 shows at the left the same positions as are shown in Fig. 40, and at the right it shows the position of one of the inking-frames after it has been separately raised through and by means of the hand driving-shaft 166, as for the purpose of permitting the lifting out of the printing-tube shaft and its parts from the press.

The controlling-engine proper.—The con-

trolling-engine, through which the main driving power of the press is directed and controlled, so as to bring about the desired motions of the carrying mechanisms of the printing, inking, and dampening devices or of any other part of the press which it is desired to move, will next be described.

In the preferred form of my improved controlling-engine shown and described herein I employ connecting mechanism between the driving mechanism of the controlling-engine and the part or parts of the press to be moved into or out of operative position, connecting the driving mechanism with said part or parts of the press, driving mechanism, preferably driven by the driving mechanism of the press, for imparting motion through the said connecting mechanism to the said part or parts of the press to be moved into or out of operative position, and suitable clutch mechanism to connect the driving mechanism with the said connecting mechanism and to disconnect them. I use connecting mechanism which is capable of motion in either direction, as I am thus enabled by the use of the same controlling mechanism to impart to the part or parts of the press to be moved a movement one way or the other, as desired, in order to move such part or parts into or out of operative position. Such motion one way or the other I obtain by employing clutch mechanism which is capable of assuming any of three separate positions, in one of which the driving mechanism is wholly disconnected from the connecting mechanism and the part or parts of the press to be moved, in which case such part or parts are at rest, and in the other two positions of which the driving mechanism and the connecting mechanism are connected with each other in one position, so as to impart motion in one direction to the connecting mechanism to move the part or parts of the press one way, as into operative position, and in the other position so as to impart motion in the opposite direction to the connecting mechanism to move the said part or parts of the press the other way, as out of operative position. My preferred form of mechanism for this purpose is shown in the drawings, and consists of two clutch gear-wheels intermediate between the main shaft of my controlling-engine and the connecting mechanism and clutch mechanism adapted to cause one or the other or neither of the clutch gear-wheels to connect the shaft with the said connecting mechanism, although, of course, any other mechanism suitable for the purpose may be employed. I will now proceed to describe the particular form of controlling-engine shown in the drawings herein.

The main driving-shaft of the machine 178, as described below, has a small beveled gear-wheel 184 on an extension of the shaft at one end, as shown in Figs. 37 and 38. This meshes with a beveled gear-wheel 185 on the main shaft 186 of the controlling-engine and drives the same. On this shaft 186 and re-

volving with the same are also the clutch 187 (controlled by the lever 188) and the beveled gear-wheel 189. The clutch 187 can be moved on the shaft 186 lengthwise of the shaft. 5 Loosely mounted rotatively on this main shaft 186 of the controlling-engine are the two clutch-wheels 190 and 191, each of them held from longitudinal movement on the shaft and both having beveled gears meshing with 10 the beveled gear-wheel 192. The latter is on a short shaft having at its other end a smaller beveled gear-wheel meshing with a beveled gear-wheel at the bottom of a short shaft having a worm 193 meshing with a worm-wheel 194 on the end of the shaft 167, which, as 15 heretofore described, moves all the damping-frames simultaneously toward or from their respective printing-surfaces. The lever 188 has three possible positions, as shown 20 in Fig. 38^a. When it is in the central position, (shown in Fig. 38,) the clutch 187 is held centrally between the clutch-wheels 190 and 191, and hence is unlocked or unclutched from both. At such time the wheels 190, 25 and 192 are at rest and with them the shaft 167 and damping-frames 115. When the lever 188 is thrown to one side, as shown 30 in Fig. 38^a, the clutch 187 is moved toward the clutch-wheel 190, locks or clutches with the same, and so drives it, and through it the gear-wheel 192 and shaft 167, and thereby simultaneously swings all the damping-frames 115. When the lever 188 is thrown to the 35 other side, the clutch 187 is moved toward the clutch-wheel 191, locks or clutches with the same, and drives it, and through it the gear-wheel 192 (but now in the opposite direction) and shaft 167, and thereby simultaneously swings all the damping-frames 115 back again. Thus through control of the 40 three positions of the clutch 187 the damping-frames can be swung toward or from the printing-surfaces or left at rest at any point, and this as often and as far and as long as desired. 45 The further action of the controlling-engine is as follows: The beveled gear-wheel 189 on the main shaft 186 of the controlling-engine meshes with two beveled gear-wheels 195 and 196, which turn loosely on the shaft 197. On the shaft 197 and revolving with it are the sliding clutch 198 (between the beveled gear-wheels 195 and 196) and the two beveled gear-wheels 199 and 200, the latter being preferably both on this one shaft, as shown. The 50 clutch 198 is controlled by the lever 201, this lever, like lever 188, having three possible positions, those positions determining whether the clutch 198 (and so the shaft 197) shall be locked with the gear-wheel 195 or with the gear-wheel 196 or shall be unlocked from both, the shaft 197 as a consequence being either driven in one direction or driven in the other direction or not driven at all. The beveled gear-wheel 199 at the left end of shaft 197, as 55 shown in Fig. 37, meshes with a beveled gear-wheel at the end of a short shaft 202. This shaft has a worm at its upper end meshing

with a worm-wheel on the end of the shaft 149, which shaft, through the mechanism already described, moves all the printing-surfaces simultaneously out from or in toward the main impression - drum. The beveled gear-wheel 200 (at the right end of shaft 197, as shown in Fig. 37) meshes with a beveled gear-wheel on the lower end of shaft 158, 75 which through mechanism heretofore described moves all the inking-frames simultaneously in toward or out from the printing-surfaces. Thus through control of the lever 201 the printing - surfaces and the inking-frames can be moved, the one toward or from the impression-surface and the other toward or from their printing-surfaces and as often and as far as desired and preferably all simultaneously, as shown. The calculations 80 for speed are very carefully made, so that the proper relative movements of the several parts are secured. The motions are so greatly reduced by the connections shown, and thereby become so slow, that the control can safely 85 be by hand, as described. Nevertheless, if desired, a safety-clutch of any well-known and approved form might be introduced in proper place, as at the point 184 185, which would unclutch whenever abnormal resistance was offered to the further motion of the 90 controlling - engine main shaft 186. The damping-frames have a separate controlling-lever in order that they may be independently manipulated, as it is important that the 95 printing-surfaces should be well damped, and completely and thoroughly, before there is any contact of the inking-surfaces with them at the beginning of the printing operation, and also that the printing - surfaces 100 should be well and thoroughly damped after the inking-surfaces have been moved out of contact with them at the end of the 105 printing operation.

In practice on starting up the press, as in 110 the morning, the damping-frames are first swung in toward the printing-surfaces and until the form-dampening rollers contact with same, and the parts are then allowed to run until the printing-surfaces are all thoroughly 115 dampened. The damping-frames are then swung back out of the way. The ink-frames and printing-surfaces are then swung in and down until they are in operative printing position, the printing-surfaces on the impression-drum and the form-inking rollers on the printing-surfaces. The damping-frames are then swung in a second time until the form-dampening rollers contact with the printing-surfaces and are in operative printing position. All this time all the parts are running. The printing then proceeds. In stopping, as at night, the several motions of the damping-frames, printing-surfaces, and inking-frames 125 may occur simultaneously, as by throwing 130 both levers 188 and 201 over together. The directing or controlling of a portion of the main driving power of the machine to do the work of raising and lowering the printing-

surfaces simultaneously is an improvement of importance, as is also the directing of a portion of the main driving power to do the work of swinging the entire series of ink-frames simultaneously toward and from the printing-surfaces and the directing of a portion of the same power to do the work of swinging the entire series of damping-frames simultaneously toward and from the printing-surfaces.

In the form of controlling-engine shown in the drawings the driving mechanism of the controlling-engine consists of the shaft 186 and its connections. The connecting mechanism between it and the damping-frames consists of the train of gearing comprising gear 192 and its shaft and gearing connecting the shaft with the damping-frames. The connecting mechanism between it and the ink-frames 20 consists of the train of gearing comprising shaft 197, gear 200, and the other gearing connecting them with the ink-frames, and the connecting mechanism between the said driving mechanism and the printing-surfaces consists of the train of gearing comprising shaft 197, gear 199, and the other gearing connecting them with the printing-surfaces. The clutch mechanism to connect the driving mechanism of the controlling-engine with 30 the damping-frames through the connecting mechanism consists of clutch 187 and the two clutch gear-wheels 190 and 191, intermediate between shaft 186 and gear 192 and its shaft and connecting-gearing. Similarly the clutch mechanism to connect the driving mechanism of the controlling-engine with the inking mechanism and the printing-surfaces consists of clutch 198 and clutch gear-wheels 195 and 196, intermediate between shaft 186 and 40 shaft 197.

In the drawings I have shown the connecting mechanism or the train of gearing connecting with the damping mechanisms as driven separately by means of the shaft of gear 192 through a gear-wheel at the other end of the shaft. It is of course evident that the train of gearing connecting with the inking mechanisms or that connecting with the printing-surfaces or that leading to any other part of the press could similarly be separately driven, if desired. I have also shown in the drawings shaft 197 as driving the trains of gearing connecting with the printing-surfaces and with the inking mechanisms. It is of course evident that the same shaft could also, if desired, drive the train of gearing connecting with the damping mechanisms or with any other part of the press by merely connecting such train with shaft 197 by suitable gearing. Thus one or more shafts, as desired, can be employed for the purpose of driving the various trains of gearing.

In the drawings in this case my controlling-engine has been shown as controlling the movements of the printing, inking, and damping devices only; but it can of course be applied to control the movements of any other

part of the press which it may be desired to move into or out of operative position.

The driving mechanism of my controlling-⁷⁰ engine may be driven from any suitable source of power, although I prefer to drive it, as shown in the drawings, by the driving mechanism of the press. In the preferred form of my improved devices, as shown, the ⁷⁵ connecting mechanisms intervening between the driving mechanism of the controlling-engine and the different parts of the press are shown as consisting of trains of gearing. They may consist, however, of any other ⁸⁰ form of mechanism suitable for the purpose. Likewise the means for operating the clutch mechanisms need not be levers, but may be any suitable means for controlling the clutch mechanism.

The main drum.—The driving mechanism for the main drum 49 is new. Its power is great and is applied to the main drum out from the center and near where the work of the drum is done. The driving mechanism ⁹⁰ is shown especially in Figs. 1, 2, 3, 4, 5, 10, and 38. The main driving-shaft 178 is a four-inch shaft and is solidly mounted in the central legs of the main frame of the machine. It is driven by any suitable motor. The main ⁹⁵ driving-shaft 178 has a small gear-wheel near each end, each of which meshes with a large gear-wheel on the outer end of a secondary driving-shaft 181. Each of these secondary driving-shafts 181 is a five-inch shaft, has its ¹⁰⁰ bearings in the main circular frame on one side of the drum, and has at its inner end inside the drum a small gear-wheel which meshes with an internal gear 182, bolted fast to the internal face of the periphery of the drum ¹⁰⁵ near the edge of the drum. This drives the drum. The drum is carried on a six-inch shaft 183, running through the center of the machine and carried by the two main circular frames, which have two circular bushings to ¹¹⁰ that end, as shown in the drawings.

The impression-surface of the drum 49, that is to receive and carry the paper 48, is made suitably yielding and elastic as follows: The drum is of iron and is turned rough on ¹¹⁵ its outer surface, as with a coarse thread or a file-like surface, and slightly under the required full working diameter. A mixture of unvulcanized rubber is made, such as on vulcanization will become very hard, and is applied in its unvulcanized condition to the rough exterior surface of the iron drum and in proper and regular thickness. Then a different mixture of unvulcanized rubber is made, such as on vulcanization will not become so hard, and is applied also in its unvulcanized condition to the drum on the outside of and covering the first layer and in proper and regular thickness. Woven belting of stout material is then wound very ¹²⁰ tightly around this compound layer of unvulcanized rubber on the drum, covering it all and with many layers. The whole drum is then moved into the vulcanizing-furnace,

and the compound layer of rubber is thereby vulcanized and hardened *in situ* and substantially integrated with the solid iron of the drum, all seams and jointings disappearing, 5 the internal layer becoming almost as hard as the iron and substantially integrating with the iron of the drum, and the outer layer becoming suitably hard and yet not so hard as the inner layer, but suitably elastic and yielding for lithographic-printing purposes, and 10 the outer layer integrating with the inner layer, so that the whole body of rubber is securely integrated with the iron drum and is yet sufficiently soft and yielding on its outer 15 surface. The belt wrappings are removed, and the surface is turned and rubbed and polished and trimmed until it is in proper condition. The resulting rubber surface of the drum is seamless and compact and im- 20 movably united with the drum, so that there is no danger of its shifting on the drum or of its rolling up before the printing-surfaces or blistering even under the very great pressures involved in the operation of the ma- 25 chine. The rubber has proper exterior surface density and elasticity for the purposes of the lithographic printing in the combinations described, but is of such increasing density and hardness inwardly in its mass 30 that the strains tending to wholly tear or disrupt the rubber from its integration with the iron of the drum are reduced to a minimum.

The paper 48 is held in place on the rubber face of the drum 49 by means of a series 35 of grippers, the construction of which involves some elements of novelty. These grippers and connected parts are shown in Figs. 3, 4, 10, 11, 12, 13, and 14. To release the grip, the gripper-head 203 is first raised from 40 the drum-face and then turned or rotated from over the drum-face. This permits the paper to freely leave the drum. To retake its grip after passing the point of entrance of the fresh paper to the drum, the motions are 45 reversed, the gripper-head being first turned or rotated back over the drum-face and then brought down tightly onto the paper on that face. To move the gripper-head 203 toward and from the face of the drum, I provide a 50 carrying and sliding rod 204, which is mounted in a bracket 205, screwed fast near the edge of the drum. The rod is keyed in this bracket, as shown in Figs. 12 and 14, to keep it from turning or rotating, but it is free to 55 slide up and down in the bracket. The rod has a head at both ends to keep it in place, the lower head having a roller 206. Against the lower head a stout spring 207 presses, constantly tending to force the rod downward 60 and so to bring the gripper-head down onto the drum-face and to hold it firmly there. Any suitable pressure brought to bear on the roller 206 of the lower head of the rod can drive the rod up against the force of the 65 spring 207 and so raise the gripper-head from the drum-face. The cam 208, carried on a bracket bolted to the main circular frame of

the machine, Figs. 3, 4, and 10, is in the path of motion of the rollers 206 as they revolve with the drum and furnishes such pressure 70 at the proper time and so raises the several gripper-heads 203 from the drum-face as they come around to it by forcing the rod 204 up against the power of the spring 207. As soon as the end of this cam 208 is reached the 75 rod and gripper-head snap back to their former position under stress of the spring. The cam 208 is of such length and position, Fig. 3, as to raise the gripper-heads and hold them raised as they pass the point where the paper 80 leaves and enters the press. To turn or rotate the gripper-head 203 from over the drum-face after it has been raised from the drum-face, I mount it on a sleeve 209, loose rotatively on the rod 204, but under the constant 85 rotative stress of a spring 210, tending to rotate it against a stop 211 on the bracket 205, and so to rotate and hold the gripper-head over the drum-face in the position shown in Fig. 12. The sleeve 209 carries a projecting 90 roller 212. Any suitable pressure on the roller 212 can rotate the sleeve 209 against the force of the spring 210 and so rotate the gripper-head 203 from over the face of the drum. The cam 213, mounted on and constituting a 95 part of the same bracket of the main circular frame of the press that carries the cam 208, furnishes this pressure, and so rotates the gripper-head against the force of the spring. When its pressure is released, the gripper-head 100 flies back to its position over the face of the drum. The cam 213 is so placed in the press and is of such length that the gripper-heads are all rotated from over the face of the drum at the place where the paper 105 leaves and fresh paper enters the press. The cams 208 and 213 are so placed and proportioned that the grippers as they revolve with the drum strike first the cam 208, which raises them, then the cam 213, which rotates 110 them, then after an interval they leave the cam 213, which permits them to rotate back, and then they leave the cam 208, which permits them to snap down onto the paper.

At the bottom of the press, where the paper 115 enters and leaves, is a bracket 214 on each side of the press, (see Figs. 3, 4, and 10,) bolted to the main circular frame. It carries the entering-roller 215, over which the paper passes on entering the press, and also the 120 roller 216, around which the paper passes on leaving the press. The entering-roller 215 is carried in adjustable bearings, whereby the pressure of its frictional contact with the drum may be regulated. The adjustability 125 is attained by slideways in the bracket 214, radial with respect to the impression-drum and sliding boxes therein adjusted by set-screws and constituting the bearings of the roller. The outer end of this slideway is 130 hinged and held in place by a spring-catch, whereby the roller is removable in a manner similar to the construction shown at 124 and 125 in Fig. 29, except that it is the end and

not the side of the slideway that is hinged. The roller 216 is a shaft having three or four small rubber wheels of slightly-larger diameter than the shaft merely to guide and support the paper on its passage out of the press without smearing it. This roller 216 is mounted and is adjustable in a manner entirely like entering-roller 215.

Below the impression-drum are two paper 10 guide-rollers, as shown in Fig. 3, the one turning in sliding bearings, and thereby by its weight tending to maintain a constant tension on the entering paper 48. Any other well-known means may be employed for this purpose—as, for instance, a brake on the paper-roll.

To mount and hold the paper-roll, there is a bracket 217 at each side of the roll projecting outwardly from the press and having an 20 inclined upper edge up which to roll the end of the shaft of the paper-roll and a receiving and holding slot for that end to drop into. This is shown in Figs. 1, 2, and 3. Any of the well-known means may be employed to 25 feed the paper from the roll reliably in line.

The main frame of the machine consists of two heavy W-shaped legs 47, one on each side, and two main circular frames 46, one on each side. The legs 47 (see Figs. 1, 2, 3, 4, 5, and 30 37) furnish a wide base for the machine and are arranged radially with respect to the drum, being triple-rayed, and so strong and compact, and are securely bolted to the circular frames 46 by a series of heavy bolts circularly 35 arranged. The two circular frames (one on each side of the press) are securely bolted together by a series of long bolts or tie-rods 45 and are shaped, as shown in the drawings, to adapt them to their various offices. The legs 40 47 rest upon and are securely bolted to two heavy side bed-beams 44, one on each side, which are connected to each other by three cross bed-beams 43, having flanges and bolted to the side beams. The bed-beams rest on a 45 brick foundation.

In practical use for multicolor lithographic-printing purposes the press herein described and shown presupposes such a preliminary preparation of the series of printing-surfaces 50 before they come to the press, both with respect to the artist's work and with respect to the transerrer's work, as is set out, for instance, in my pending method application heretofore referred to, Serial No. 695,281, filed November 2, 1898, and especially such transferring to the printing-surfaces in accurate and related register throughout the whole series as is set out, for instance, in my pending application for transfer-presses, Serial No. 55 703,082, filed January 23, 1899, Serial No. 732,437, filed October 4, 1899, and Serial No. 568,795, filed November 13, 1895. Assuming such preparation of the series of printing-surfaces, the permanent adjustment or adaptation of the printing-press to such a related system of transferring is attained in the following manner: The parts of the printing-

press are constructed in size and proportions to effect exact registry when the printing-surfaces receive accurate and related registers, as referred to above, and are introduced into the printing-press in proper meshing relationship to its parts. This proper meshing relationship must be experimentally determined when the press is for the first time 75 used; but having been so determined it may be conveniently and permanently retained by marking, at any given position of the press as a whole, the several gear-wheels 144 and their several meshing gear-wheels 145, where they come together, the tooth of the one that at such time takes into a recess of the other—marked tooth in marked recess. Thus whenever a printing-tube is removed and the same or another one is inserted again it is only necessary to see to it that the gears 144 and 145 80 so mesh that the marked tooth of the one will take into the marked recess of the other.

The ink-fountains and the water-rollers are charged in any desired way. In selecting the 90 colors for the several ink-fountains and connected groups of inking-rollers for successive printing jobs it will be found useful to employ the same color always in the same ink-fountain and connected group of inking-rollers. In practice a series or scale of standard 95 colors may be found useful, the artist building his pictures up with those standard colors and any given group of inking-rollers on the press always applying one and the same 100 standard color. This will avoid the necessity of keeping duplicate or triplicate sets of rollers for each press and will minimize the amount of cleaning up of the rollers that is necessary.

In starting up the press it is important always to first thoroughly dampen the printing-surfaces, which may be done through and by means of the controlling-engine, as heretofore described. While the press is running 110 for this purpose, the several groups of inking-rollers will coincidentally be thoroughly inked from their respective ink-fountains. This having been accomplished, the parts are brought down into operative printing position by means of the controlling-engine, as heretofore described, and the printing proceeds thereafter automatically. The paper is fed continuously through the machine and continuously delivered to any suitable 120 delivering and cutting devices. Each printing-surface prints its color in succession upon a given surface of the paper-web as that surface passes in succession under each one of them, and when this part of the paper emerges from 125 the machine the picture upon it is completed. Meantime other impressions have been following the first continuously, and completed pictures are continuously delivered from the machine. Each printing-surface operates 130 continuously, and all fifteen are printing simultaneously as many different impressions, which together when superposed at the same place on the same paper and in exact register

with each other constitute the finished picture. A single press such as is shown in the drawings will do the work and take the place of about one hundred presses of the kind now in use in printing lithographs in fifteen colors. This is because this one press will print fifteen colors simultaneously, and, moreover, so much time is saved in the handling of the prints that my improved press will print about 5 four thousand seven hundred complete fifteen-color lithographs in the same time that it would require one of the present-style presses to print seven hundred copies in a single color. Moreover, additional economy 10 is secured in the saving of space for the presses, of labor of workmen in handling the presses and the prints, and of time in turning out the work.

The present invention insures the realization 15 of multicolor lithographic printing with a practically-unlimited number of colors, and as the last operatively of a cycle of inventions all addressed to that end it is with them of the first importance and value in the art. 20 It permits of practically pure color-printing 25 in multicolor lithography, of more artistic work, of more durable printing-surfaces, and of more accurate coloring and registry. It permits of any desired order in the printing 30 of the colors with marked artistic advantage. It permits and attains quickness, economy, and perfection in the printing, avoiding the losses and errors of many separate feedings and separate printings. It applies to the 35 most sensitive and delicate methods of color-printing known, the fastest and cheapest methods of printing possible, for the entire series of printing-surfaces are working continuously and simultaneously, and a plurality 40 of pictures are being simultaneously printed, and each picture is being printed in all its colors at one continuous operation in time less than the time of one revolution of the paper-carrying drum or cylinder, and a plurality 45 of finished pictures are delivered at each complete revolution of the drum. The speed of the paper-web under the printing-surfaces may be as great as or greater than that of the paper sheets over the flat lithographic-printing surfaces in common use. 50

For the purposes of the several claims hereinafter made many detailed variations might be made in the mechanisms without departing from my invention.

55 What I claim as new, and desire to secure by Letters Patent, is—

1. In the inking mechanism of a press a swinging ink-frame consisting of two side frames 65, a connecting-shaft 66 to which the 60 side frames are keyed, and a tie-rod 67, one of the side frames having a suitable segmental gear or worm wheel, in combination with suitable ink-distributing rollers and form-inking rollers carried by the ink-frame, one 65 of said form-inking rollers being loosely mounted on the tie-rod, and with suitable

swinging mechanism, substantially as and for the purposes set forth.

2. In the inking mechanism of a press a swinging ink-frame consisting of two side 70 frames 65, a connecting-shaft 66 to which the side frames are keyed, and a tie-rod 67, one of the side frames having a suitable segmental gear or worm wheel, in combination with a suitable swinging mechanism and with a 75 main ink-distributing cylinder loosely mounted on the shaft 66 and with suitable ink-distributing rollers and form-inking rollers carried by the ink-frame, substantially as and for the purposes set forth. 80

3. In the inking mechanism of a press a swinging ink-frame having two side frames 65 and a connecting-shaft 66 to which the side frames are secured, one of the side frames having a suitable segmental gear or 85 worm wheel, in combination with suitable driving mechanism and with a main ink-distributing cylinder loosely mounted on the shaft 66 and with suitable ink-distributing rollers and form-inking rollers carried by the 90 ink-frame, substantially as and for the purposes set forth.

4. In combination with the impression-surface of a printing-press having two suitable gears, and positive driving mechanism, of a 9 printing-surface having gear connection with one of said gears and positively driven thereby and a main ink-distributing cylinder for said printing-surface having gear connection with the other of said gears and positively 100 driven thereby, substantially as and for the purposes set forth.

5. In combination with the impression-surface of a printing-press having two suitable gears, and positive driving mechanism, of a 105 printing-surface having gear connection with one of said gears and positively driven thereby and a main ink-distributing cylinder for said printing-surface having gear connection with the other of said gears and positively 110 driven thereby, and suitable ink-distributing rollers having gear connection with the main ink-distributing cylinder and positively driven thereby, substantially as and for the purposes set forth. 115

6. The combination with a suitable impression-surface, a suitable damping mechanism, a swinging ink-frame having carrying-shaft, and a doctor-roller and suitable ink-distributing rollers carried by the ink-frame, of a 120 main ink-distributing cylinder loosely mounted on the shaft and carrying on its hub at one end a gear-wheel having gear connection with the impression-surface and driven thereby and an internal cam-groove reciprocating 125 the doctor-roller, and at the other end a gear-wheel having gear connection with the ink-distributing rollers and driving them, an internal cam-groove reciprocating the doctor-roller and a second internal cam-groove reciprocating the water-supply roller, substantially 130 as and for the purposes set forth.

7. The combination with the main ink-distributing cylinder having on its hub at each end a wheel carrying an internal groove reciprocating the ductor-roller, of a ductor-roller carried by slides reciprocated by the said internal grooves, said ductor-roller being adjustable in the slides, substantially as and for the purposes set forth.
8. In the inking mechanism of a press an ink-feeding roller, a pawl-and-ratchet mechanism connected with same to give it a step-by-step rotative motion, a swinging frame carrying the inking mechanism and supported in the main frame of the machine, a reciprocating rod supported in slideways in the main frame of the machine and suitable mechanism to reciprocate it, and a connecting-link, the link being pivoted at one end to the reciprocating rod and at the other end being adjustably pivoted to the pawl-and-ratchet mechanism, whereby with a fixed reciprocation of the rod a faster or slower rotative motion of the ink-feeding roller may be attained and maintained whatever the position of the swinging frame, substantially as and for the purposes set forth.
9. The combination with a suitable ink-fountain and ink-feeding roller, of a pawl-and-ratchet mechanism connected with the ink-feeding roller and having a slideway 114 in one arm of the ratchet-lever, a swinging frame carrying the inking mechanism and supported in the main frame of the machine, a reciprocating rod 112 supported in slideways in the main frame of the machine and suitable mechanism to reciprocate it and a connecting-link 113 pivoted at one end to the rod 112 and at the other end adapted to be secured at any desired point in the slideway, whereby with a fixed reciprocation of the link a faster or slower rotative motion of the ink-feeding roller may be attained and maintained whatever the position of the swinging frame, substantially as and for the purposes set forth.
10. In a printing-press the combination, with a group of ink-distributing rollers and suitable driving and ink-supplying and ink-receiving mechanisms, of a reciprocatable lifting-plate having mechanism to positively control at the limits of its reciprocations the individual positions of the ink-distributing rollers and mechanism to reciprocate the plate, whereby the ink-distributing rollers may be forced positively into operative positions by one motion of the lifting-plate and may be forced positively therefrom by the reverse motion of the lifting-plate, substantially as and for the purposes set forth.
11. In a printing-press the combination, with a group of ink-distributing rollers and suitable driving and ink-supplying and ink-receiving mechanisms, of a reciprocatable lifting-plate having adjustable mechanism to control at the limits of its reciprocations the individual positions of the ink-distributing rollers and mechanism to reciprocate the

plate, whereby the ink-distributing rollers may be forced positively but adjustably into operative positions by one motion of the lifting-plate and may be forced positively therefrom by the reverse motion of the lifting-plate, substantially as and for the purposes set forth. 70

12. In a printing-press, the combination, with a group of ink-distributing rollers and suitable driving and ink-supplying and ink-receiving mechanisms, of a reciprocatable lifting-plate having mechanism to control at the limits of its reciprocations the individual positions of the ink-distributing rollers and mechanism to reciprocate the plate and a stop to positively limit the motion of the plate in the direction toward the ink-receiving mechanism, whereby the ink-distributing rollers may be forced positively into operative positions by one full motion of the lifting-plate and may be forced positively therefrom by the reverse motion of the lifting-plate, substantially as and for the purposes set forth. 75 80 85 90

13. In a printing-press, the combination, with a group of ink-distributing rollers and suitable driving and ink-supplying and ink-receiving mechanisms, of a reciprocatable lifting-plate having mechanism to control at the limits of its reciprocations the individual positions of the ink-distributing rollers and mechanism to reciprocate the plate and stops to positively limit the motion of the plate in each direction, whereby the ink-distributing rollers may be forced positively into operative positions by one full motion of the lifting-plate and may be forced positively therefrom by the reverse full motion of the lifting-plate, substantially as and for the purposes set forth. 95 100 105

14. In a printing-press the combination, with a group of ink-distributing rollers and suitable driving and ink-supplying and ink-receiving mechanisms, of a reciprocatable lifting-plate having adjustable mechanism to control at the limits of its reciprocations the individual positions of the ink-distributing rollers and mechanism to reciprocate the plate and a stop to positively limit the motion of the plate in the direction toward the ink-receiving mechanism, whereby the ink-distributing rollers may be forced positively but adjustably into operative positions by one full motion of the lifting-plate and may be forced positively therefrom by the reverse motion of the lifting-plate, substantially as and for the purposes set forth. 110 115 120 125

15. In a printing-press the combination, with a group of ink-distributing rollers and suitable driving and ink-supplying and ink-receiving mechanisms, of a carrying-frame carrying the ink-distributing rollers in slideways angularly arranged with reference to each other, and a reciprocatable lifting-plate also carried by the said frame and having mechanism to control at the limits of its reciprocations the individual positions of the ink-distributing rollers in their respective 130

slideways in the carrying-frame, and mechanism to reciprocate the lifting-plate, whereby the ink-distributing rollers may be forced positively together into operative position by 5 one motion of the lifting-plate and rendered separable from each other and from adjacent rollers by the reverse motion of the lifting-plate, substantially as and for the purposes set forth.

16. In a printing-press the combination, with a group of ink-distributing rollers and suitable driving and ink-supplying and ink-receiving mechanisms, of a carrying-frame carrying the ink-distributing rollers in slide- 15 ways angularly arranged with reference to each other, and a reciprocatable lifting-plate also carried by the said frame and having adjustable mechanism to control at the limits of its reciprocations the individual positions of 20 the ink-distributing rollers in their respective slideways in the carrying-frame, and mechanism to reciprocate the lifting-plate, whereby the ink-distributing rollers may be forced positively but adjustably together into operative 25 position by one motion of the lifting-plate and rendered separable from each other and from adjacent rollers by the reverse motion of the lifting-plate, substantially as and for the purposes set forth.

17. In a printing-press the combination, with a group of ink-distributing rollers and suitable driving and ink-supplying mechanisms and a group of form-inking rollers, of an ink-frame and mechanism to move it, said 35 ink-frame carrying the form-inking rollers in fixed operative positions and carrying the ink-distributing rollers in slideways, and a lifting-plate also carried by the said frame and having mechanism to control at the limits 40 of its motions the individual positions of the ink-distributing rollers in their respective slideways in the carrying-frame and mechanism to move the lifting-plate, whereby the ink-distributing rollers may be forced positively 45 into operative position in contact with the form-inking rollers by one motion of the lifting-plate and may be forced positively therefrom by the reverse motion of the lifting-plate, and the form-inking rollers may be 50 collectively moved out of and into operative contact with the printing-surface, substantially as and for the purposes set forth.

18. In a printing-press the combination, with a group of ink-distributing rollers and suitable driving and ink-supplying mechanisms and a group of form-inking rollers, of an ink-frame and mechanism to move it, said ink-frame carrying the form-inking rollers in adjustably-fixed operative positions and carrying the ink-distributing rollers in slide- 55 ways, and a lifting-plate also carried by the said frame and having adjustable mechanism to control at the limits of its motions the individual positions of the ink-distributing rollers in their respective slideways in the carrying-frame and mechanism to move the lifting-plate, whereby the ink-distributing 60

rollers may be forced positively but adjustably into operative position in contact with the form-inking rollers by one motion of the 70 lifting-plate and may be forced positively therefrom by the reverse motion of the lifting-plate, and the form-inking rollers may be separately adjusted and collectively moved out of and into operative contact with the 75 printing-surface, substantially as and for the purposes set forth.

19. In a printing-press the combination, with a group of ink-distributing rollers and suitable driving and ink-supplying mechanisms and a group of form-inking rollers, of an ink-frame and mechanism to move it, said 80 ink-frame carrying the form-inking rollers in fixed operative positions and carrying the ink-distributing rollers in slideways, and a lifting-plate 85 also carried by the said frame and having mechanism to control at the limits of its motions the individual positions of the ink-distributing rollers in their respective slide- ways in the carrying-frame and mechanism to move the lifting-plate, and a stop limiting the motion of the ink-frame in the direction of the printing-surface and a stop limiting the motion of the lifting-plate in the direction of the form-inking rollers, whereby the ink- 90 distributing rollers may with certainty be forced positively into operative position in contact with the form-inking rollers by one full motion of the lifting-plate and may be forced positively therefrom by the reverse 95 motion of the lifting-plate, and the form-inking rollers may be collectively moved out of and into positive operative contact with the printing-surface, substantially as and for the purposes set forth. 100

20. In a printing-press the combination, with a group of ink-distributing rollers and suitable driving and ink-supplying mechanisms and a group of form-inking rollers, of an ink-frame and mechanism to move it, said 110 ink-frame carrying the form-inking rollers in adjustably-fixed operative positions and carrying the ink-distributing rollers in slide-ways, and a lifting-plate also carried by the said frame, and having adjustable mechanism to control at the limits of its motions the individual positions of the ink-distributing rollers in their respective slideways in the carrying-frame and mechanism to move the lifting-plate, and a stop limiting the motion of 115 the ink-frame in the direction of the printing-surface and a stop limiting the motion of the lifting-plate in the direction of the form-inking rollers, whereby the ink-distributing rollers may with certainty be forced positively 120 but adjustably into operative position in contact with the form-inking rollers by one full motion of the lifting-plate and may be forced positively therefrom by the reverse motion of the lifting-plate, and the form-inking rollers 125 may be separately adjusted and collectively moved out of and into positive operative contact with the printing-surface, substantially as and for the purposes set forth. 130

21. In a printing-press the combination, with a group of ink-distributing rollers and suitable driving and ink-supplying mechanisms and a group of form-inking rollers, of an ink-frame and mechanism to move it, said ink-frame carrying the form-inking rollers in adjustably-fixed operative positions and carrying the ink-distributing rollers in slideways, and a lifting-plate also carried by the said frame, and having adjustable mechanism to control at the limits of its motions the individual positions of the ink-distributing rollers in their respective slideways in the carrying-frame and mechanism to move the lifting-plate, and an adjustable stop limiting the motion of the ink-frame in the direction of the printing-surface and a stop limiting the motion of the lifting-plate in the direction of the form-inking rollers, whereby the ink-distributing rollers may with certainty be forced positively but adjustably into operative position in contact with the form-inking rollers by one full motion of the lifting-plate and may be forced positively therefrom by the reverse motion of the lifting-plate, and the form-inking rollers may be separately adjusted and collectively moved out of and into positive but collectively-adjustable operative contact with the printing-surface, substantially as and for the purposes set forth.

22. In the inking mechanism of a printing-press, the combination, substantially as set forth, of movable side frames 65, shaft 89, eccentrics 88 having stops 92, lifting-plates 100, and collars 91 having stops 93.

23. In the inking mechanism of a printing-press, the combination, substantially as set forth, with movable side frames 65 having slideways, of roller-carrying sliding boxes 94 therein and laterally extended, and lifting-plates 100 having recesses 95.

24. In the inking mechanism of a printing-press, the combination, substantially as set forth, with movable side frames 65 having slideways, of roller-carrying sliding boxes 94 therein and laterally extended, and lifting-plates 100 having recesses 95, the upper or outer ends or walls of said recesses being adjustable.

25. In the inking mechanism of a printing-press, the combination, substantially as set forth, with movable side frames 65 having slideways, of roller-carrying sliding boxes 94 therein and laterally extended, and lifting-plates 100 having recesses 95 and guiding-slots 87, one or more of the slideways in the movable frame being arranged angularly with respect to the guiding-slots 87 and the corresponding recesses 95 being correspondingly wider than the sliding boxes 94.

26. In the inking mechanism of a printing-press, the combination, substantially as set forth, with suitable frames having slideways, of roller-carrying sliding boxes 94 therein and laterally extended, and lifting-plates 100 having recesses 95 and guiding-slots 87, one or more of the slideways in the frame being

arranged angularly with respect to the guiding-slots 87 and the corresponding recesses 95 being correspondingly wider than the sliding boxes 94.

27. In the inking mechanism of a printing-press, the combination, substantially as set forth, with suitable frames having slideways, of roller-carrying sliding boxes 94 therein and laterally extended, and lifting-plates 100 having recesses 95, the upper or outer ends or walls of said recesses being adjustable, and guiding-slots 87, one or more of the slideways in the frame being arranged angularly with respect to the guiding-slots 87 and the corresponding recesses 95 being correspondingly wider than the sliding boxes 94.

28. In the inking mechanism of a printing-press, the combination, substantially as set forth, with a suitable frame having slideways, of a roller-carrying sliding box 94 therein and laterally extending therefrom, a reciprocatable lifting-plate 100 carried by the frame, guiding-slots 87 to guide its reciprocation and a recess 95 to receive the extended sliding box having an adjustable upper or outer end or wall 96, the slideway in the frame being arranged angularly with respect to the guiding-slots 87 and the recess 95 being correspondingly wider than the extended sliding box 94.

29. The combination, with suitable impression and printing surfaces and suitable inking mechanism including a main ink-distributing cylinder, of a dampening mechanism including rollers positively driven by the main ink-distributing cylinder, and a swinging damping-frame carrying said dampening mechanism, the damping-frame being centered with the main ink-distributing cylinder, and mechanism to swing the damping-frame, substantially as and for the purposes set forth.

30. The combination, with suitable impression and printing surfaces and suitable inking mechanism including a main ink-distributing cylinder, of a dampening mechanism having a water-supply roller, a metal rider and form-dampening rollers, and a swinging damping-frame carrying said dampening mechanism, the damping-frame being centered with the main ink-distributing cylinder, and the water-supply roller and metallic rider being positively driven with said main ink-distributing cylinder, and mechanism to swing the damping-frame, substantially as and for the purposes set forth.

31. The combination, with suitable impression and printing surfaces and suitable inking mechanism including a main ink-distributing cylinder, of a dampening mechanism having a metal rider and form-dampening rollers, and a swinging damping-frame carrying said dampening mechanism, the damping-frame being centered with the main ink-distributing cylinder, and the metallic rider being positively driven with said main ink-distributing cylinder, and mechanism to

swing the damping-frame, substantially as and for the purposes set forth.

32. The combination of a suitable driving gear-wheel, a swinging damping-frame centered therewith and mechanism to swing it, a water-supply roller, a metal rider, and form-dampening rollers, all carried by the damping-frame, the water-supply roller reciprocating in slideways in the damping-frame toward and away from the metal rider and having mechanism to reciprocate it, and a series of gear-wheels positively connecting the water-supply roller and the metal rider with the driving gear-wheel, said series of gear-wheels including a chain of movable gear-wheels driving the reciprocating water-supply roller and carried on a chain of pivoted links, substantially as and for the purposes set forth.

33. The combination of a suitable driving gear-wheel, a swinging damping-frame centered therewith and mechanism to swing it, a water-supply roller, a metal rider, and form-dampening rollers, all carried by the damping-frame, the water-supply roller reciprocating in slideways in the damping-frame to and away from the metal rider and having mechanism to reciprocate it, and being removable from said slides and from said mechanism, and a series of gear-wheels positively connecting the water-supply roller and the metal rider with the driving gear-wheel, said series of gear-wheels including a chain of movable gear-wheels driving the reciprocating water-supply roller and carried on a chain of pivoted links, the water-supply roller being removable from the last of said chain of links, substantially as and for the purposes set forth.

34. The combination of a swinging damping-frame and mechanism to swing it, suitable dampening-rollers including a water-supply roller carried by the damping-frame, the water-supply roller reciprocating in slideways in the damping-frame and having mechanism to reciprocate it, said mechanism including a revolving cam or eccentric centered with the swinging damping-frame, substantially as and for the purposes set forth.

35. The combination with swinging damping-frame 115 and mechanism to swing it, of the water-supply roller 119 reciprocating in slideways in the damping-frame, carrying lever-arms 137 mounted in the damping-frame, revolving cam-groove 134 centered with the damping-frame, roller-pin 135 and guiding-link 136, substantially as and for the purposes set forth.

36. The combination of a suitable driving gear-wheel, a swinging damping-frame centered therewith and mechanism to swing it, a water-supply roller, a metal rider, and form-dampening rollers, all carried by the damping-frame, the water-supply roller reciprocating in slideways in the damping-frame to and away from the metal rider and having mechanism to reciprocate it, said mechanism in-

cluding a revolving cam or eccentric centered with and revolving with said driving gear-wheel, and a series of gear-wheels positively connecting the water-supply roller and the metal rider with the driving gear-wheel, said series of gear-wheels including a chain of movable gear-wheels driving the reciprocating water-supply roller and carried on a chain of pivoted links, substantially as and for the purposes set forth.

37. In combination with the water-supply roller revolving in its bearings and reciprocating in slideways in its carrying-frame, and mechanism to revolve and mechanism to reciprocate it and having end angle-piece or coupling 123, of the locking-guide 139 carried by said frame and having extended locking-face for the angle-piece 123 to slide upon, whereby the latter is kept from revolving while being permitted to reciprocate, substantially as and for the purposes set forth.

38. The combination with a cylindrical lithographic-printing surface having two gear-wheels, of a suitable impression-surface having two gears, one gear meshing directly with one of the gear-wheels of the printing-surface, and a chain of links and a chain of gear-wheels carried by the links and meshing at one end of the chain with the remaining gear of the impression-surface and at the other end with the remaining gear-wheel of the printing-cylinder, substantially as and for the purposes set forth.

39. The combination with a series of cylindrical lithographic-printing surfaces having each two gear-wheels, of a main impression-drum having two gears, one gear meshing directly with one of the gear-wheels of each of the printing-surfaces, and a series of chains of links and a series of chains of gear-wheels carried by the links and meshing at one end of each chain with the remaining gear of the main drum and at the other end with the remaining gear-wheel of each printing-cylinder, substantially as and for the purposes set forth.

40. The combination with a removable tubular lithographic-printing surface and supporting form-cylinder having a gear-wheel at each end of same, said form-cylinder being removable from its mountings, and one of said gear-wheels being smaller than the other and smaller than said tubular printing-surface, of a main impression-drum having a gear at each side of same, one larger than the other, the larger gear at one side meshing directly with the larger gear-wheel of the form-cylinder, and on the other side a chain of links and a chain of gear-wheels carried by the links and meshing at one end of the chain with the smaller gear of the main drum and at the other end with the smaller gear-wheel of the form-cylinder, substantially as and for the purposes set forth.

41. The combination with a series of removable tubular lithographic-printing surfaces and supporting form-cylinders each having a

- gear-wheel at each end, said form-cylinders being removable from their mountings and said tubular printing-surfaces being removable from their supporting form-cylinders, 5 and one of said gear-wheels in the case of each form-cylinder being smaller than the other and smaller than said tubular printing-surfaces, of a main impression-drum having a gear at each side of same, one larger than the other, the larger gear at one side meshing directly with the series of larger gear-wheels of the form-cylinders, and on the other side a series of chains of links and a series of chains of gear-wheels carried by the links and meshing at one end of each chain with the smaller gear of the main drum and at the other end with the smaller gear-wheels of the form-cylinders, substantially as and for the purposes set forth.
- 15 42. The combination with a main impression-drum and a series of suitable printing-surfaces arranged around it and a series of pressure-bars carrying the printing-surfaces, of a revolvable shifting disk or plate and mechanism to revolve or shift it, and a series of toggle-levers pivoted to the frame at their outer ends and to the pressure-bars at their inner ends and to the revolvable shifting disk or plate at their center pivots, substantially as and for the purposes set forth.
- 20 43. The combination with a suitable impression-drum and a series of suitable printing-surfaces arranged around the drum, and a series of groups of inking-rollers and a series of ink-frames carrying the form-inking rollers of said groups, of a series of separate mechanisms to move the ink-frames, one for each ink-frame, and a central driving mechanism to simultaneously actuate the separate moving 25 mechanisms, the separate moving mechanisms being detachably secured to the central driving mechanism, substantially as and for the purposes set forth.
- 25 44. The combination with a suitable impression-drum and a series of suitable printing-surfaces arranged around the drum, and a series of groups of inking-rollers and a series of ink-frames carrying the form-inking rollers of said groups, of a series of separate 30 moving mechanisms to move the ink-frames, one for each ink-frame, and a central driving mechanism to simultaneously actuate the separate moving mechanisms, the separate moving mechanisms being detachably secured to the central driving mechanism, and a series of separate 35 moving mechanisms, one for each ink-frame, to actuate the moving mechanism when detached from the central driving mechanism, substantially as and for the purposes set forth.
- 30 45. The combination of driving-rod 70, cap 163, lock 164, worm 162 and worm-wheel segment 68, substantially as and for the purposes set forth.
- 35 46. The combination of driving-rod 70, cap 163, lock 164, key 165, worm 162 and worm-

wheel segment 68, substantially as and for the purposes set forth.

47. The combination of driving-rod 70, cap 163, lock 164, driving-shaft 166, worm 162 and worm-wheel segment 68, substantially as and for the purposes set forth.

48. The combination of a central driving mechanism, a series of rods 70 simultaneously driven thereby, a series of caps 163, a series 75 of locks 164, a series of worms 162 and a series of worm-wheel segments 68, substantially as and for the purposes set forth.

49. The combination of a central driving mechanism, a series of rods 70 simultaneously 80 driven thereby, a series of caps 163, a series of locks 164, a series of separate driving-shafts 166, a series of worms 162 and a series of worm-wheel segments, 68, substantially as and for the purposes set forth.

50. The combination, with a suitable driving mechanism including a worm 162, of an ink-frame and inking-rollers carried by the ink-frame, the ink-frame consisting of two side frames 65, a shaft 66 to which the side 90 frames are keyed fast, a worm-wheel segment 68 secured to one of said side frames, and a suitable binding-rod, substantially as and for the purposes set forth.

51. The combination, with a suitable driving mechanism including a worm 162, of an ink-frame and inking-rollers carried by the ink-frame, the ink-frame consisting of two side frames 65, a shaft 66 to which the side 95 frames are keyed fast, a worm-wheel segment 68 secured to one of said side frames, and a suitable binding-rod, and a main ink-distributing cylinder centered with the shaft 66, substantially as and for the purposes set forth.

52. The combination with a suitable impression-drum and a series of suitable printing-surfaces arranged around the drum and a series of groups of inking-rollers and a series of ink-frames carrying the form-inking rollers of said groups, of a series of separate 105 moving mechanisms to move the ink-frames, one for each ink-frame, and a central driving mechanism to simultaneously actuate the separate moving mechanisms, each separate moving mechanism being adjustable with respect to the central driving mechanism, substantially as and for the purposes set forth.

53. The combination with a suitable impression-drum and a series of suitable printing-surfaces arranged around the drum and a series of groups of inking-rollers and a series of ink-frames carrying the form-inking rollers of said groups, of a series of separate 110 moving mechanisms to move the ink-frames, one for each ink-frame, and a central driving mechanism to simultaneously actuate the separate moving mechanisms, each separate moving mechanism being adjustable with respect to the central driving mechanism, substantially as and for the purposes set forth.

54. The combination with a suitable impression-drum and a series of suitable printing-surfaces arranged around the drum and a series of groups of inking-rollers and a series of ink-frames carrying the form-inking rollers of said groups, of a series of separate 115 moving mechanisms to move the ink-frames, one for each ink-frame, and a central driving mechanism to simultaneously actuate the separate moving mechanisms, each separate moving mechanism being adjustable with respect to the central driving mechanism, substantially as and for the purposes set forth.

55. The combination with a suitable impression-drum and a series of suitable printing-surfaces arranged around the drum and a series of groups of inking-rollers and a series of ink-frames carrying the form-inking rollers of said groups, of a series of separate 120 moving mechanisms to move the ink-frames, one for each ink-frame, and a central driving mechanism to simultaneously actuate the separate moving mechanisms, each separate moving mechanism being adjustable with respect to the central driving mechanism, and adjustable stops to limit the motion of each 125 ink-frame toward its printing-surface, substantially as and for the purposes set forth.

56. The combination with a suitable impression-drum and a series of suitable printing-surfaces arranged around the drum and a series of groups of inking-rollers and a series of ink-frames carrying the form-inking rollers of said groups, of a series of separate 130 moving mechanisms to move the ink-frames, one for each ink-frame, and a central driving mechanism to simultaneously actuate the separate moving mechanisms, each separate moving mechanism being adjustable with respect to the central driving mechanism, and adjustable stops to limit the motion of each ink-frame toward its printing-surface, substantially as and for the purposes set forth.

54. The combination with a suitable impression-drum and a series of suitable printing-surfaces arranged around the drum and a series of groups of inking-rollers and a series of ink-frames carrying the form-inking rollers of said groups, of a series of separate moving mechanisms to move the ink-frames, one for each ink-frame, and a central driving mechanism to simultaneously actuate the separate moving mechanisms, and adjustable stops to limit the motion of each ink-frame toward its printing-surface, substantially as and for the purposes set forth.

55. The combination with a suitable impression-drum and a series of suitable printing-surfaces arranged on the impression-face of the drum, of a series of groups of dampening-rollers, a series of damping-frames carrying the same, a central actuating device to simultaneously move said frames toward and from the printing-surfaces, and a series of connecting mechanisms connecting said central actuating device with the several damping-frames, substantially as and for the purposes set forth.

56. The combination with a suitable impression-drum and a series of suitable printing-surfaces arranged on the impression-face of the drum, of a series of groups of dampening-rollers, a series of damping-frames carrying the same, a central actuating device to simultaneously move said frames toward and from the printing-surfaces, and a series of separately-adjustable connecting mechanisms connecting said central actuating device with the several damping-frames, substantially as and for the purposes set forth.

57. The combination with a suitable impression-surface and a suitable printing-surface and a group of dampening-rollers and a movable damping-frame carrying the same, of a suitable oscillating device 171 and mechanism to oscillate it, lever-arms 173 and 175, and links 176, substantially as and for the purposes set forth.

58. The combination with a suitable impression-surface and a suitable printing-surface and a group of dampening-rollers and a movable damping-frame carrying the same, of a suitable oscillating device 171 and mechanism to oscillate it, lever-arms 173 and 175, and adjustable links 176, substantially as and for the purposes set forth.

59. The combination with a suitable impression-drum and a series of suitable printing-surfaces arranged on the impression-face of the drum, of a series of groups of dampening-rollers, a series of movable damping-frames carrying the same, a central oscillating device 171 and mechanism to oscillate it, a series of levers 173, 175, and a series of links 176, substantially as and for the purposes set forth.

60. The combination, with a suitable impression-drum and a series of printing-surfaces arranged around it and a suitable main driving mechanism driving the drum and the

printing-surfaces positively together, of carrying mechanism for carrying said printing-surfaces and moving them simultaneously in toward or out from the impression-drum and so into and out of operative position and a controlling-engine connected on the one side with said main driving mechanism and on the other side with the carrying mechanism of said printing-surfaces, and controlled independently of the regular printing operation of the printing-press, whereby the printing-surfaces may, prior to the beginning of the printing operation, be brought into suitable permanent printing pressure contact with the drum, by the main driving mechanism of the press, be positively and permanently held in such pressure contact so long as the printing operation is proceeding, and may then be moved into permanent position out of contact with the drum by the main driving mechanism of the press, substantially as and for the purposes set forth.

61. The combination with a suitable impression-drum and a series of printing-surfaces arranged around it and a series of groups of inking-rollers and a series of movable ink-frames carrying the same and a suitable main driving mechanism driving the drum and the printing-surfaces and some of the ink-rollers all positively together, of moving mechanism for simultaneously moving said ink-frames in toward or out from the printing-surfaces and a controlling-engine connected on the one side with said main driving mechanism and on the other side with the moving mechanism for simultaneously moving the ink-frames, substantially as and for the purposes set forth.

62. The combination, with a suitable impression-drum and a series of printing-surfaces arranged around it and a series of groups of dampening-rollers and a series of movable damping-frames carrying the same and a suitable main driving mechanism driving the drum and the printing-surfaces and some of the dampening-rollers all positively together, of moving mechanism for simultaneously moving said damping-frames in toward or out from the printing-surfaces and a controlling-engine connected on the one side with said main driving mechanism and on the other side with the moving mechanism for simultaneously moving the damping-frames, substantially as and for the purposes set forth.

63. The combination, with a suitable impression-drum and a series of printing-surfaces arranged around it and a series of groups of inking-rollers and a series of movable ink-frames carrying the same, of a controlling-engine connected with said ink-frames and with the carrying devices of said printing-surfaces and constructed to simultaneously move said printing-surfaces toward or from the impression-drum and said ink-frames toward or from the printing-surfaces, substantially as and for the purposes set forth.

64. The combination, with a suitable impression-drum and a series of printing-sur-

faces arranged around it and a series of groups of inking-rollers and a series of movable ink-frames carrying the same, and a series of groups of damping-rollers and a series of movable damping-frames carrying the same, of a controlling-engine connected with said ink-frames and with said damping-frames and with the carrying devices of said printing-surfaces and constructed to move said printing-surfaces toward or from the impression-drum and said ink-frames toward or from the printing-surfaces, and said damping-frames toward or from the printing-surfaces, substantially as and for the purposes set forth.

15 65. The combination, with a suitable impression-drum and a series of printing-surfaces arranged around it and a series of groups of inking-rollers and a series of movable ink-frames carrying the same, and a series of groups of dampening-rollers and a series of movable damping-frames carrying the same, of a controlling-engine connected with said ink-frames and with said damping-frames and with the carrying devices of said printing-surfaces and constructed to simultaneously move said printing-surfaces toward or from the impression-drum and said ink-frames toward or from the printing-surfaces and to independently move said damping-frames toward or from the printing-surfaces, substantially as and for the purposes set forth.

20 66. The combination with a suitable impression-drum and a series of suitable printing-surfaces arranged around it and a suitable main driving mechanism, of a series of groups of dampening-rollers and a series of movable damping-frames carrying the same and moving mechanism to move them simultaneously toward or from the printing-surfaces, and a controlling-engine including a sliding clutch capable of occupying three axial positions, and two clutch-wheels fixed axially, the said sliding clutch and fixed clutch-wheels being connected on the one side with the main driving mechanism and on the other side with the moving mechanism for simultaneously moving the damping-frames, substantially as and for the purposes set forth.

25 67. The combination with a suitable impression-drum and a series of suitable printing-surfaces arranged around it, and a series of groups of inking-rollers and a series of movable ink-frames carrying the same and a suitable main driving mechanism, of moving mechanism for simultaneously moving said ink-frames in toward or out from the printing-surfaces and a controlling-engine including a sliding clutch capable of occupying three axial positions, and two clutch-wheels fixed axially, the said two fixed clutch-wheels and said sliding clutch being connected, on the one side with the main driving mechanism and on the other side with the moving mechanism for simultaneously moving the ink-frames, substantially as and for the purposes set forth.

30 68. The combination, with a suitable im-

pression-drum and a series of printing-surfaces arranged around it and a suitable main driving mechanism, of a carrying mechanism 70 for carrying said printing-surfaces and moving them simultaneously in toward or out from the impression-drum and a controlling-engine including a sliding clutch capable of occupying three axial positions and two clutch-wheels fixed axially, the said two clutch-wheels and said sliding clutch being connected, on the one side with the main driving mechanism and on the other side with the carrying mechanism of said printing-surfaces, 75 substantially as and for the purpose set forth.

69. In a press, the combination with a suitable impression-drum and a series of suitable printing-surfaces, of a series of grippers consisting each of a spring-actuated reciprocating carrying-rod 204 and a spring-actuated 85 rotating sleeve 209 carrying the gripper-head, and cams 208 and 213, substantially as and for the purposes set forth.

70. In a lithographic-printing press, the combination with a suitable impression surface or surfaces, of a series of interior form-supports, a corresponding series of exterior removable and replaceable hollow lithographic printing-forms carried by the form-supports, and mechanism for moving the same into and out of contact with the impression-surface, substantially as and for the purposes set forth.

71. In a lithographic-printing press, the combination with a main impression-drum, of 100 a series of interior form-supports arranged on the impression-face of the drum and positively driven with the drum, and a corresponding series of exterior removable and replaceable hollow printing-forms carried by the 105 form-supports, and mechanism for moving the same into and out of contact with the impression-surface, said mechanism being controlled at will and independently of the printing operations of the drum but centered with the drum, and operatively connected with the form-supports, substantially as and for the purposes set forth.

72. In a lithographic-printing press, the combination with a main impression-drum, of 115 a series of interior form-supports arranged on the impression-face of the drum and positively driven with the drum, and a corresponding series of exterior removable and replaceable hollow printing-forms carried by the form-supports, and mechanism for simultaneously moving the same into and out of contact with the impression-surface, said mechanism being controlled at will and independently of the printing operations of the drum but centered 120 with the drum, and operatively connected with the form-supports, substantially as and for the purposes set forth.

73. In a lithographic-printing press, the combination with a main impression-drum, of 130 a series of interior form-supports arranged around it and adapted to carry a corresponding series of removable and replaceable hollow printing-forms, a series of radially-mov-

able sliding boxes carrying the form-supports, a series of pressure-bars carrying the sliding boxes, a series of links connected to the pressure-bars, a revoluble shifting device connected to the links and controlled at will and independently of the printing operations of the drum but centered with the drum, and adapted by partial revolution to simultaneously move the form-supports toward and from the impression-surface of the drum, and a series of suitable dampening and inking devices, the inking devices being carried on a series of movable frames, and mechanism for moving the said frames outwardly and inwardly, substantially as and for the purposes set forth.

74. In a lithographic - printing press, the combination with a main impression-drum, of

a series of interior form-supports arranged around it and adapted to carry a corresponding series of exterior removable and replaceable lithographic-printing forms, means for adjusting the positions of the form-supports with respect to the drum, means for moving the form-supports toward and from the drum, 25 a series of suitable dampening and inking devices, and means for moving the inking devices toward and from the form-supports, substantially as and for the purposes set forth.

In testimony whereof I have signed my name to this specification in the presence of two subscribing witnesses.

EDWARD HETT.
